3,235,358

CONTROL OF UNDESIRABLE VEGETATION
Edward J. Soboczenski, Chadds Ford, Pa., assignor to
E. I. du Pont de Nemours and Company, Wilmington,
Del., a corporation of Delaware
No Drawing. Filed Sept. 6, 1962, Ser. No. 221,890
11 Claims. (Cl. 71—2.5)

This application is a continuation-in-part of copending applications Serial No. 89,673, filed February 16, 1961; and Serial No. 12,956, filed March 7, 1960, both now abandoned.

This invention relates to the use of 3,5-substituted uracils as herbicides, and is more particularly directed to herbicidal compositions and methods employing, as an active ingredient, at least one compound of the formula

(1)

where:

R is

Alkyl of 1 through 10 carbon atoms,
Substituted alkyl of 1 through 10 carbon atoms,
Aryl of 5 through 14 carbon atoms,
Substituted aryl of 5 through 14 carbon atoms,
Aralkyl of 5 through 15 carbon atoms,
Substituted aralkyl of 5 through 15 carbon atoms,
Alkenyl of 3 through 10 carbon atoms,
Alkynyl of 3 through 10 carbon atoms,
Cycloalkyl of 3 through 12 carbon atoms,
Cycloalkenyl of 4 through 12 carbon atoms,
Cycloalkyl alkyl of 4 through 13 carbon atoms,
Cycloalkenyl alkyl of 5 through 13 carbon atoms,
(Substituted cycloalkyl)alkyl of 5 through 14 carbon atoms,
(Substituted cycloalkenyl)alkyl of 5 through 14 carbon atoms,
Or cyano;

R₁ is chlorine, fluorine, bromine, iodine, methyl, ethyl, propyl, butyl, methoxy, ethoxy, propoxy, butoxy, nitro, alkoxyethyl of 2 through 6 carbon atoms, hydroxy alkyl of 1 through 6 carbon atoms, alkenyl of 3 through 6 carbon atoms, thiocyanato, cyano, methylthiol, alkylthio of 1 through 4 carbon atoms, methylthiomethyl, chloromethyl, bromomethyl, fluoromethyl, phenylthiomethyl, or carboxymethylthiomethyl,

with the proviso that R₁ can be hydrogen when R is cycloalkyl, cycloalkenyl, cycloalkyl alkyl, or cycloalkenyl alkyl;

and

X is oxygen or sulfur.

The salts of these compounds can also be used according to this invention. By "salts" is meant those compounds formed with such cations as sodium, potassium, lithium, calcium, magnesium, barium, strontium, iron, manganese and quaternary ammonium.

Some of the uracils of Formula 1 also form novel 1:1 addition compounds with nitrogenous bases. The exact structure of these compounds is not known. Although the compounds are, generally speaking, poorly soluble in water, they are, according to the best available information, believed to be essentially salt-like in structure. They will be symbolized by the following formula, with the

2

understanding that it is representative only, and is not intended to illustrate actual structure:

(2)

5

where:

R and R₁ are defined as in Formula 1,
and

NB is a nitrogenous base having an ionization constant K_b of $\geq 10^{-9}$ in water.

Suitable nitrogenous bases are substituted, unsubstituted, cyclic and acyclic

Amines,

Amidines, and
Guanidines

The amines can be primary, secondary or tertiary amines, polyamines, arylamines, or heterocyclic amines. Illustrative of such amines are:

25 Sec.-butylamine
2-amino-2-methyl-1,3-propanediol
Trimethylenediamine
Ethanolamine
Dodecylamine
30 Ethylenediamine
Hexamethylenediamine
Cocoadiamine
Tallowdiamine
Hexamethyleneimine
35 Cyclohexylamine
Methoxypropylamine
Methylamine
Dimethylamine
Trimethylamine
Ammonia
Ethylamine
35 Propylamine
Butylamine
Octylamine
Pyridine
Piperidine
40 Tetramethylguanidine
Acetamidine
Benzylamine
Diethylenediamine
2-aminobutanol-1
2-aminoctanol-1

Within the scope of Formula 1 is a group of novel compounds. These are of the formula

(3)

60

where:

65 R is phenyl, substituted phenyl, cycloalkyl, of 3 through 12 carbon atoms, cycloalkenyl of 5 through 12 carbon atoms, cycloalkyl alkyl of 4 through 13 carbon atoms, substituted cycloalkyl alkyl of 5 through 14 carbon atoms, or

70

wherein:

X is methyl or ethyl,

Y is hydrogen or methyl, and

Z is an alkyl group of less than 6 carbon atoms; and

R₁ is halogen, methyl, hydroxymethyl, methoxymethyl, or nitro;

and the salts of these compounds as defined in Formulae 1 and 2.

The substituted uracils of Formula 1 also form water stable, novel complexes with phenol and substituted phenols. These complexes have the formula

(4)

where:

R and R₁ are as defined in Formula 1,
X is hydrogen, chlorine, nitro, alkyl of 1 through 3 carbon atoms, bromine or OR₂,

R₂ is alkyl of 1 through 3 carbon atoms,

Y is chlorine or alkyl of 1 through 3 carbon atoms,

m is a number 1 through 5, and

n is 1 or 2.

These complexes are also herbicidal, and in this respect, have some advantages over the uracils per se, viz., higher solubility in oils and solvents. They are formulated into herbicidal compositions in the same way as are the uracils themselves.

In Formulae 1 to 4 and Formula 5, which follows, the term "substituted alkyl" is intended to include such radicals as

Bromoalkyl of 1 through 10 carbon atoms,

Chloroalkyl of 1 through 10 carbon atoms,

Hydroxyalkyl of 1 through 10 carbon atoms,

Alkoxyalkyl of 2 through 10 carbon atoms,

Alkoxy carbonyl alkyl of 3 through 10 carbon atoms,

Dialkyl amino alkyl of 3 through 10 carbon atoms, and

Cyanoalkyl of 2 through 10 carbon atoms.

Similarly, the terms "aryl" and "substituted aryl" embrace radicals such as

Phenyl,

Naphthyl,

o-Biphenyl,

Pyridyl,

Chlorophenyl,

Methoxyphenyl,

Bromophenyl,

Dichlorophenyl,

Dibromophenyl,

Fluorophenyl,

Trichlorophenyl,

Alkylphenyl of 7 through 11 carbon atoms,

Dialkylphenyl of 8 through 12 carbon atoms,

Choloroalkylphenyl 7 through 10 carbon atoms,

Nitrochlorophenyl,

Nitrophenyl,

Dichloronitrophenyl,

Chloroalkoxyphenyl of 7 through 11 carbon atoms,

Trifluoromethylphenyl,

Alkylnaphthyl of 11 through 15 carbon atoms,

Chloronaphthyl,

Tetrahydronaphthyl, and

Indenyl.

The terms "aralkyl" and "substituted aralkyl" are intended to include such radicals as

Furfuryl,

Benzyl,

Phenylalkyl of 8 through 11 carbon atoms (total),

Chlorobenzyl,

Dichlorobenzyl,

Alkylbenzyl of 8 through 11 carbon atoms (total),

Dialkylbenzyl of 9 through 13 carbon atoms (total),

Nitrobenzyl,

Alkoxybenzyl of 8 through 11 carbon atoms (total), and

Naphthylmethyl.

The terms "cycloalkyl," "cycloalkenyl," "cycloalkyl alkyl," and "cycloalkenyl alkyl" will include

Cyclohexyl,

Cyclohexenyl,

Cyclohexylalkyl,

Cyclohexenyl alkyl,

Cyclooctyl,

Cyclododecyl,

Cyclopentyl,

Cyclopentenyl,

Cyclopentyl alkyl,

Cyclopentenyl alkyl,

Norbornyl,

Norbornenyl,

Norbornyl alkyl,

Norbornenyl alkyl,

Bicyclo (2,2,2) octyl,

Bicyclo (2,2,2) octenyl,

Bicyclo (2,2,2) octyl alkyl,

Bicyclo (2,2,2) octenyl alkyl,

Cyclopropyl,

Cyclobutyl,

Cyclobutyl alkyl,

Cyclobutenyl,

Cyclobutenyl alkyl,

Hexahydroindanyl,

Tetrahydroindanyl,

Hexahydroindenyl,

Hexahydroindenyl alkyl,

Tetrahydroindanyl alkyl,

Hexahydroindanyl alkyl,

Hexahydro-4,7-methanoindenyl,

Tetrahydro-4,7-methanoindanyl,

Hexahydro-4,7-methanoindanyl,

Hexahydro-4,7-methanoindenyl alkyl,

Tetrahydro-4,7-methanoindanyl alkyl,

Hexahydro-4,7-methanoindanyl alkyl,

Decahydronaphthyl,

Decahydronaphthyl alkyl,

Tetrahydronaphthyl,

Tetrahydronaphthyl alkyl,

Decahydro-1,4-methanonaphthyl,

Decahydro-1,4-methanonaphthyl alkyl,

Octahydro-1,4-methanonaphthyl,

Octahydro-1,4-methanonaphthyl alkyl,

Decahydro-1,4,5,8-dimethanonaphthyl,

Decahydro-1,4,5,8-dimethanonaphthyl alkyl,

Octahydro-1,4,5,8-dimethanonaphthyl,

Octahydro-1,4,5,8-dimethanonaphthyl alkyl.

These cyclic substituents can be further substituted with alkyl groups of 1 through 4 carbon atoms, methoxy, chlorine and bromine.

UTILITY

These compounds' broad spectrum herbicidal activity makes them useful wherever general weed control is required, such as on industrial sites, on railroad ballast and in noncrop agricultural areas. For example, a pre-emergence treatment with these compounds will control such germinating broadleaf weeds as pigweed, lamb's quarter, mustard, chickweed and ragweed, and such grass weeds as crab grass and foxtails.

The uracils can also be used in soil foliage applications for the control of such broadleaves as pigweed, lamb's quarter, mustard, chickweed and ragweed and such grass

weeds as crab grass, foxtails, quack grass and seedling Johnson grass.

Certain of the uracils exhibit selective herbicidal action in crops. For example, by properly selecting a uracil of the invention and a rate and time of application, annual weeds growing in fields of peanuts can be controlled. This selective activity is described in greater detail in the examples which follow.

The concentration at which the compounds are to be used will vary according to the result desired, the type of vegetation, the formulation used, the mode of application, weather conditions, foliage density, and other similar factors. Since so many factors play a role it is not possible to indicate a concentration suitable for all situations. Generally, when they are used in pre-emergence treatments, the uracils are used at concentrations of from 0.25 to 5 pounds of active ingredient per acre. Concentrations of from 0.5 to 4 pounds per acre are preferred. When used in soil-foliation applications, the uracils are used at concentrations of from 10 to 35 pounds of active ingredient per acre. The optimum concentration to be used in any particular application will be readily apparent to one skilled in the art.

Preferred for use according to this invention because of their greater effectiveness at lower rates of application are compounds of the formula

where:

R is

Alkyl of 2 through 8 carbon atoms,
Substituted alkyl of 2 through 8 carbon atoms,
Phenyl, substituted phenyl,
Aralkyl of 5 through 10 carbon atoms,
Substituted aralkyl of 5 through 10 carbon atoms,
Cycloalkyl of from 3 through 12 carbon atoms,
Substituted cycloalkyl of from 4 through 12 carbon atoms,
Cycloalkenyl of 5 through 12 carbon atoms,
Substituted cycloalkenyl of 5 through 12 carbon atoms,
Cycloalkyl alkyl of 4 through 13 carbon atoms,
(Substituted cycloalkyl)alkyl of 4 through 13 carbon atoms,

and

R₁ is chlorine, bromine, iodine, methyl, hydroxymethyl, methoxymethyl, or nitro.

PREPARATION OF COMPOUNDS

The substituted uracils used according to this invention can be prepared according to the following equations:

The cyclohexylurea of Equation 6 is condensed with the α -methyl oxalacetate in an inert solvent such as benzene, and in the presence of an acidic catalyst such as phosphoric acid. This reaction mixture is heated until approximately the theoretical amount of water has been removed. This will vary according to the starting materials used. The solvent is then removed and the residue is heated at reflux with a slight excess of aqueous sodium hydroxide, whereupon ring closure takes place. The resulting uracil carboxylic acid is decarboxylated to the desired uracil by heating it above its melting point, either by itself or in an inert, high-boiling-point liquid such as dibutyl phthalate or a eutectic mixture of diphenyl and diphenyl ether.

Other uracils can be prepared by substituting an appropriate substituted urea or thiourea for the cyclohexylurea in Equation 6.

By substituting ethyl oxalacetate, α -cyano, α -fluoro, α -alkoxy, α -alkenyl, α -alkylthio, or α -alkyl oxalacetate for the α -methyl oxalacetate in Equation 6, the corresponding 5-unsubstituted, 5-cyano, 5-fluoro, 5-alkoxy, 5-alkenyl, 5-alkylthio and 5-alkyl uracils can be prepared.

Uracils substituted in the 3-position can be prepared according to the equations which follow. These 3-substituted uracils can then be converted to 3,5-di-substituted uracils for use according to this invention.

In Equation 9, a mixture of malononitrile, sec.-butylurea and triethyl orthoformate, in molar ratios of 1:1:3, is heated at 70° C. to 100° C. with stirring for 1 to 3 hours. The excess ortho ester and ethanol are then removed at reduced pressure. The residue consists of essentially pure [(3-butylureido)methylene]malononitrile.

This is dissolved in alcohol and converted to 3-sec.-butyl-5-cyanocytosine by treatment with sodium methylate, as illustrated in Equation 10.

The 3-sec.-butyl-5-cyanocytosine is converted to the corresponding uracil according to Equation 11 by a 3-hour reflux with 3 N hydrochloric acid. The uracil crystallizes from the aqueous solution on cooling.

On refluxing the 3-sec.-butyl-5-cyanouracil with an excess of 25% sodium hydroxide solution, the nitrile is hydrolyzed according to Equation 12 with the formation of 3-sec.-butyl-5-uracil carboxylic acid.

The acid is easily decarboxylated by heating it at a temperature above its melting point. This is illustrated by Equation 13. The result 3-sec.-butyluracil is purified by recrystallization from solvents such as nitromethane or carbon tetrachloride.

3,5-di-substituted uracils can also be prepared from the 3-substituted uracils made according to Equations 9 to 13 by reacting them with electrophilic reactants according to the following equation:

where A is bromine, chlorine, iodine, CH_2OH , $-\text{SCN}$, CH_2Cl , or NO_2 .

Other methods for preparing the uracils used according to this invention are set forth in J. Chem. Soc., 1956, 1877 and in J. Am. Chem. Soc., 74, 4267 (1952).

The salts of the compounds of Formula 1 are prepared by conventional methods such as dissolving the free uracil in an aqueous or nonaqueous solution of at least an equimolar amount of a base or basic salt containing the desired cation. For example, a sodium salt can be prepared by dissolving the uracil in water containing an equimolar amount of sodium hydroxide. The salt can then be isolated from the solution by removal of the water. The uracil salts which are not soluble in water can be prepared by treating an aqueous solution of an alkali metal salt of the uracil with an aqueous solution of a water-soluble salt of the metal.

The quaternary ammonium salts of the compounds of Formula 1 are prepared by reacting the substituted uracil with an appropriate quaternary ammonium hydroxide. Since these hydroxides are generally available in solution, the reaction is most conveniently carried out in the same solvent. If the salt is desired, it can be easily prepared by removing the solvent.

Alternatively, the quaternary ammonium salts of the uracils can be prepared in a dry inert solvent such as toluene, methanol or xylene by first preparing the corresponding sodium salt in the solvent. The appropriate quaternary ammonium halide is then added with stirring and, if necessary, mild heating. The sodium halide which forms is removed by filtration, leaving the quaternary ammonium salt of the uracil in solution. If desired, the dry salt can be prepared by removing the solvent, preferably in vacuo.

The nitrogenous base-addition compounds of Formula 2 are prepared by mixing together equimolar quantities of an appropriate uracil and a nitrogenous base. The mixture is gradually heated, with stirring, until a clear melt is formed. On cooling, the addition compound crystallizes. This product can then be recrystallized from a solvent such as benzene, cyclohexane, nitromethane or acetonitrile.

It is sometimes advantageous to use an inert solvent medium to carry out the reaction. Such a solvent moderates the reaction by acting as a heat sink, and allows better control of the reaction, especially if it is being car-

ried out on a large scale. Suitable inert solvents are benzene, cyclohexane, nitromethane, acetonitrile and dioxane.

When an inert solvent is used, the addition compounds are prepared by dissolving the amine in the solvent and then adding the uracil gradually, with stirring. Stirring is continued for from ten minutes to two hours. Mild heating may be necessary. Some addition compounds precipitate and can be removed by filtration. Other addition compounds are purified by evaporating the solvent. The addition compounds prepared in this way are suitable for use without further purification. However, they can be recrystallized as described above.

In some instances the uracil and amine are highly soluble in the inert solvent, but the addition compound is not, and so it can be filtered off pure when the reaction is complete.

The complexes of Formula 4 are formed by melting the uracil and phenol in a 1:1 to 2:1 (uracil:phenol) ratio. They can also be formed by codissolving the reactants, in the same ratio, in a nonpolar solvent such as nitromethane or a mixture of nitromethane and cyclohexane. If the solvent-free complex is desired, it can be isolated by evaporating the solvent, preferably in vacuo. The complexes prepared in this way are suitable for formulation and herbicidal use without further purification.

HERBICIDAL COMPOSITIONS

The uracil compounds described in Formulae 1 through 4 can be prepared for use by incorporating them with 30 adjuvants.

The amount of herbicide in such preparations can vary over a wide range according to need. Generally speaking, they will contain from about 0.5 to 95%, by weight of a uracil.

Powder and dust preparations can be made by mixing uracils of the invention with finely-divided solids such as talcs, natural clays, pyrophyllite, diatomaceous earth; flours such as walnut shell, wheat, redwood, soya bean and cotton seed; or inorganic substances such as magnesium carbonate, calcium carbonate, calcium phosphate, sulfur and lime. These preparations are made by thoroughly blending the active ingredient and the solid. The particles in such preparations are preferably less than 50 microns in average diameter.

Water-soluble preparations can be prepared by mixing a uracil with an alkaline solubilizing agent. Solid bases having a pH of at least 9.5 in a 1% aqueous solution such as sodium or potassium phosphates, silicates, carbonates, borates, oxides or hydroxides are suitable. The preparations can contain from 0.5 to 80% of active ingredient and from 5 to 99.5% of the solubilizing agent.

Granules and pellets can be made by mixing a finely-divided uracil with a suitable clay such as kaolinite, montmorillonite or attapulgite, moistening this mixture with 55 from 15 to 20% by weight of water, and then extruding the mass through a suitable die under pressure. The extrusions are cut into predetermined lengths and then dried. These pellets can be granulated if desired.

Granules or pellets can also be prepared by spraying 60 a suspension or solution of a uracil onto the surface of a preformed granule of clay, vermiculite or other suitable granular material. If the uracil is in solution, it will penetrate into the pores of the granule and so will adhere without the aid of a binding agent. When the active material is insoluble in the liquid and is carried as a suspension, it is preferable that a binding agent such as goulac, dextrin, swollen starch, glue or polyvinyl alcohol be added. In either case, the granule is then dried and ready for use.

The uracils can also be prepared in non-aqueous liquids. Aliphatic and aromatic hydrocarbons, especially those derived from petroleum and having boiling points of from 125° C. to 400° C. are preferred. Hydrocarbons having lower boiling points should not be used because of their undesirable volatilization characteristics and inflammabil-

ity. These liquid preparations are made by milling the components in a mill such as a pebble mill until the particles have average diameters of from 1 to 50 microns, preferably 5 to 20 microns.

The herbicidal preparations, whatever physical form they take, can also contain a surface-active agent. The surfactant renders the preparations readily dispersible in liquids and improves their action on waxy leaves and the like. For general application, surface-active agents are used in the preparations at concentrations of from about 1 to 10% by weight. Levels of from 0.5 to 6 parts of surfactant for each part of uracil, however, give unusual and unexpected results. Preparations having these higher levels of surfactants show greater herbicidal effectiveness than can be expected from a consideration of activity of the components used separately.

The term "surface-active agent" is intended to include wetting agents, dispersing agents, suspending agents and emulsifying agents. Surface-active agents suitable for use are set forth in "Detergents and Emulsifiers . . . Up-to-Date," 1962, John W. McCutcheon, Inc., Morristown, New Jersey. Other surface-active agents which can be used in these preparations are listed in U.S. Patents 2,139,276; 2,412,510; 2,426,417; 2,655,447; and Bulletin E-607 of the Bureau of Entomology and Plant Quarantine of the U.S. Department of Agriculture.

The preparations can also optionally contain adhesives such as gelatin, blood albumin and such resins as rosin alkyd resins. These increase retention and tenacity of deposits following application.

The alkali metal salts of the compounds of Formula 1 are especially advantageous for use as herbicides because they are soluble in water and can be applied as aqueous solutions.

With respect to the nitrogenous base-addition compounds of Formula 2, it has been found that preparation with polar low-molecular weight amines such as ethanolamines, propanolamines and butanolamines gives addition compounds which are soluble in water, especially when the amine is present in excess. Other amines, such as 40 piperidine and octanolamines give addition compounds which are soluble in both water (with an excess of amine present) and hydrocarbon solvents. At the other end of the scale, amines such as dodecylamines, cocoaamines and tallowamines give the addition compounds high hydrocarbon solubility.

Thus, it is apparent that by properly selecting an amine and forming an addition compound with it, uracils of Formula 2 can be formulated as aqueous solutions, wettable powders, or as oil-emulsifiable or oil-extendable formulations. In this way, the nitrogenous base-addition compounds give formulation and application advantages, while still maintaining the desirable herbicidal characteristics of the parent uracils.

FORMULATIONS WITH OTHER HERBICIDES

These herbicidal uracils can be combined with each other and with other known herbicides to give compositions which have advantages over the individual components.

Among the known herbicides which can be combined with the uracils are:

Substituted ureas

3-(3,4-dichlorophenyl)-1,1-dimethylurea
3-(4-chlorophenyl)-1,1-dimethylurea
3-phenyl-1,1-dimethylurea
3-(3,4-dichlorophenyl)-3-methoxy-1,1-dimethylurea
3-(4-chlorophenyl)-3-methoxy-1,1-dimethylurea
3-(3,4-dichlorophenyl)-1-n-butyl-1-methylurea
3-(3,4-dichlorophenyl)-1-methoxy-1-methylurea
3-(4-chlorophenyl)-1-methoxy-1-methylurea
3-(3,4-dichlorophenyl)-1,1,3-trimethylurea
3-(3,4-dichlorophenyl)-1,1-diethylurea
3-(p-chlorophenoxyphenyl)-1,1-dimethylurea

These ureas can be mixed with the uracils of this invention in proportions of from 1:4 to 4:1, respectively, the preferred ratio being 1:2 to 2:1.

Substituted triazines

5 2-chloro-4,6-bis(ethylamino)-s-triazine
2-chloro-4,6-bis(isopropylamino)-s-triazine
2-chloro-4-ethylamino-6-isopropylamino-s-triazine
2-chloro-4,6-bis(methoxypropylamino)-s-triazine
10 2-methoxy-4,6-bis(isopropylamino)-s-triazine
2-ethylamino-4-(2-methoxyethylamino)-6-chloro-s-triazine
2-methylmercapto-4,6-bis(isopropylamino)-s-triazine
2-methylmercapto-4,6-bis(ethylamino)-s-triazine
15 2-methylmercapto-4-ethylamino-6-isopropylamino-s-triazine
2-methoxy-4,6-bis(ethylamino)-s-triazine
2-methoxy-4-ethylamino-6-isopropylamino-s-triazine
2-isopropylamino-4-(2-methoxyethylamino)-6-methylmercapto-s-triazine

These triazines can be mixed with the uracils of this invention in proportions of from 1:4 to 4:1, respectively, the preferred ratio being 1:2 to 2:1.

Phenols

Dinitro-o-sec.-butylphenol and its salts
Pentachlorophenol and its salts

These phenols can be mixed with the uracils of this invention in the proportions of 1:10 to 10:1, respectively, the preferred ratio being 1:5 to 5:1.

Carboxylic acids and derivatives

The following carboxylic acids and derivatives can be mixed with the uracils of this invention in the listed respective proportions:

(A)

2,3,6-trichlorobenzoic acid and its salts
2,3,5,6-tetrachlorobenzoic acid and its salts
2-methoxy-3,5,6-trichlorobenzoic acid and its salts
2-methoxy-3,6-dichlorobenzoic acid and its salts
3-amino-2,5-dichlorobenzoic acid and its salts
3-nitro-2,5-dichlorobenzoic acid and its salts
2-methyl-3,6-dichlorobenzoic acid and its salts
2,3-dichloro-6-methylbenzoic acid and its salts
2,4-dichlorophenoxyacetic acid and its salts and esters
2,4,5-trichlorophenoxyacetic acid and its salts and esters
(2-methyl-4-chlorophenoxy)acetic acid and its salts and esters
50 2-(2,4,5-trichlorophenoxy)propionic acid and its salts and esters
2-(2,4,5-trichlorophenoxy)ethyl 2,2-dichloropropionate
4-(2,4-dichlorophenoxy)butyric acid and its salts and esters
55 4-(2-methyl-4-chlorophenoxy)butyric acid and its salts and esters
2,3,6-trichlorobenzylxypropanol

Mixed in a 1:20 to 8:1 ratio, preferably a 1:8 to 4:1 ratio.

(B)

2,6-dichlorobenzonitrile

Mixed in a 1:4 to 4:1 ratio, preferably a 1:3 to 3:1 ratio.

(C)

Trichloroacetic acid and its salts

Mixed in a 1:4 to 25:1 ratio, preferably a 1:2 to 10:1 ratio.

(D)

2,2-dichloropropionic acid and its salts

Mixed in a 1:4 to 10:1 ratio, preferably a 1:2 to 5:1 ratio.

11	12
(E)	(A)
N,N-di(n-propyl)thiolcarbamic acid, ethyl ester	5,6-dihydro-(4A,6A)-dipyrido-(1,2-A,2',1'-C)pyrazinium dibromide
N,N-di(n-propyl)thiolcarbamic acid, n-propyl ester	5 Mixed in a 1:20 to 16:1 ratio, preferably a 1:5 to 5:1 ratio.
N-ethyl-N-(n-butyl)thiolcarbamic acid, ethyl ester	10 (B)
N-ethyl-N-(n-butyl)thiolcarbamic acid, n-propyl ester	3-amino-1,2,4-triazole
Mixed in a 1:2 to 24:1 ratio, preferably a 1:1 to 12:1 ratio.	10 Mixed in a 1:20 to 20:1 ratio, preferably a 1:5 to 5:1 ratio.
(F)	15 (C)
N-phenylcarbamic acid, isopropyl ester	3,6-endoxohexahydrophthalic acid
N-(m-chlorophenyl)carbamic acid, isopropyl ester	Mixed in a 1:4 to 20:1 ratio, preferably a 1:2 to 10:1 ratio.
N-(m-chlorophenyl)carbamic acid, 4-chloro-2-butyanyl ester	(D)
Mixed in a 1:2 to 24:1 ratio, preferably a 1:2 to 12:1 ratio.	Diphenylacetonitrile
(G)	N,N-dimethyl- α , α -diphenylacetamide
2,3,6-trichlorophenylacetic acid and its salts	20 N,N-di(n-propyl)-2,6-dinitro-4-trifluoromethylaniline
Mixed in a 1:20 to 8:1 ratio, preferably a 1:4 to 4:1 ratio.	N,N-di(n-propyl)-2,6-dinitro-4-methylaniline
(H)	Mixed in a 1:10 to 30:1 ratio, preferably a 1:5 to 20:1 ratio.
2-chloro-N,N-diallylacetamide	(E)
Maleic hydrazide	25 O-(2,4-dichlorophenyl)- α -methyl-isopropylphosphor- amidothioate
Mixed in a 1:2 to 10:1 ratio, preferably a 1:1 to 5:1 ratio.	2,3,5,6-tetrachloroterephthalic acid, dimethyl ester
<i>Inorganic and mixed inorganic-organic salts</i>	Mixed in a 1:4 to 20:1 ratio, preferably a 1:3 to 15:1 ratio.
The following salts can be mixed with the uracils of this invention in the listed respective proportions:	(F)
(A)	2,4-dichloro-4'-nitrodiphenyl ether
Calcium propylarsonate	Mixed in a 1:10 to 30:1 ratio, preferably a 1:5 to 20:1 ratio.
Disodium monomethylarsonate	35 (G) Other substituted uracils
Octyl-dodecylammoniummethylarsonate	The uracils used according to this invention can be mixed with other substituted uracils, in the respective proportions listed below. Methods for the preparation of the listed uracils can be found in copending applications Serial Nos. 159,746, filed December 15, 1961; 89,674, filed February 16, 1961; 167,434, filed February 1, 1962; and 89,672, filed February 16, 1961.
Dimethyl arsenic acid	40 (A)
Mixed in a 1:4 to 8:1 ratio, preferably a 1:2 to 4:1 ratio.	3-isopropyl-5-bromo-6-methyluracil
(B)	3-isopropyl-5-chloro-6-methyluracil
Sodium arsenite	3-sec.-butyl-5-bromo-6-methyluracil
Mixed in a 1:10 to 40:1 ratio, preferably a 1:5 to 25:1 ratio.	3-sec.-butyl-5-chloro-6-methyluracil
(C)	50 3-cyclohexyl-5-bromo-6-methyluracil
Lead arsenate	3-cyclohexyl-5-chloro-6-methyluracil
Calcium arsenate	3-tert.-butyl-5-bromo-6-methyluracil
Mixed in a 150:1 to 600:1 ratio, preferably a 100:1 to 400:1 ratio.	3-tert.-butyl-5-chloro-6-methyluracil
(D)	55 Mixed in a 1:4 to 4:1 ratio, preferably a 1:2 to 2:1 ratio.
Sodium tetraborate hydrated, granulated	(B)
Sodium metaborate	3-cyclohexyl-6-methyluracil
Sodium pentaborate	3-cyclohexyl-6-ethyluracil
Unrefined borate ore such as borascu	60 3-cyclohexyl-6-sec.-butyluracil
Polychlorborate	3-norbornyl-6-methyluracil
Mixed in a 6:1 to 1500:1 ratio, preferably a 3:1 to 1000:1 ratio.	3-cyclopentyl-6-methyluracil
(E)	3-cyclohexyl-6-isopropyluracil
Sodium chlorate	Mixed in a 1:4 to 4:1 ratio, preferably a 1:2 to 2:1 ratio.
Mixed in a 2:1 to 40:1 ratio, preferably a 1:1 to 20:1 ratio.	(C)
(F)	3-isopropyl-1-trichloromethylthio-5-bromo-6-methyluracil
Ammonium sulfamate	65 Mixed in a 1:4 to 4:1 ratio, preferably a 1:2 to 2:1 ratio.
Mixed in a 1:1 to 100:1 ratio, preferably a 1:1 to 50:1 ratio.	(C)
(G)	3-cyclohexyl-1-trichloromethylthio-5-bromo-6-methyluracil
Ammonium thiocyanate	70 3-cyclohexyl-1-trichloromethylthio-5-bromo-6-methyluracil
Mixed in a 1:10 to 20:1 ratio, preferably a 1:5 to 5:1 ratio.	3-sec.-butyl-1-acetyl-5-bromo-6-methyluracil
<i>Other organic herbicides</i>	3-isopropyl-1-acetyl-5-bromo-6-methyluracil
The following herbicides can be mixed with the uracils of this invention in the listed respective proportions.	75 3-isopropyl-1-trichloromethylthio-5-chloro-6-methyluracil

3-isopropyl-1-methyl-5-bromo-6-methyluracil
3-cyclohexyl-1-methyl-5-chloro-6-methyluracil
3-cyclohexyl-1,6-dimethyluracil

Mixed in a 1:4 to 4:1 ratio, preferably a 1:2 to 2:1 ratio.

(D)

3-cyclohexyl-5,6-trimethyleneuracil
3-sec.-butyl-5,6-trimethyleneuracil
3-isopropyl-5,6-trimethyleneuracil
3-cyclohexyl-5,6-tetramethyleneuracil
3-isopropyl-5,6-tetramethyleneuracil

Mixed in a 1:4 to 4:1 ratio, preferably a 1:2 to 2:1 ratio.

EXAMPLES

This invention will be better understood by referring to the following illustrative examples:

Preparation of compounds

EXAMPLE 1.—PREPARATION OF 3-CYCLOHEXYL-5-METHYLURACIL

A mixture of 56.8 parts of cyclohexylurea, 73 parts of

diethyl 2-methyl oxalacetate, and 4 parts of 85% orthophosphoric acid in 400 parts of benzene is heated at reflux for 8 hours, during which time 7.8 parts of water are collected. The solvent is removed and the residual oil taken up in 400 parts of water containing 24 parts of sodium hydroxide. The solution is heated on a steam bath with agitation for 2 hours. Acidification with concentrated hydrochloric acid causes precipitation of 3-cyclohexyl-5-methyluracil-6-carboxylic acid. This is collected by filtration, air-dried, and taken up as a suspension in 100 parts of eutectic mixture of diphenyl ether and diphenyl. This mixture is stirred and heated at reflux, whereupon CO_2 is evolved. Upon completion of the CO_2 evolution, the mixture is cooled, filtered, and the solvent washed out with benzene. Crystalline 3-cyclohexyl-5-methyluracil remains.

The following compounds are prepared as in Example 1 by substituting equivalent amounts of mono substituted ureas and thioureas and equivalent amounts of oxalacetates set forth in the following table for the cyclohexylurea and diethyl- α -methyl oxalacetate:

Oxalacetate	Parts by weight	Urea	Parts by weight	Substituted uracil product
Diethyl 2-methyloxalacetate	73	Butylurea	46.3	3-butyl-5-methyluracil.
Do	73	1-(4-methoxycyclohexylmethyl)urea	70.8	3-(4-methoxycyclohexylmethyl)-5-methyluracil.
Diethyl 2-propyloxalacetate	84	Allylthiourea	46.4	3-allyl-5-propyl-2-thiouacil.
Diethyl 2-butyloxalacetate	90	Propynylurea	39.2	3-propynyl-5-butyloxuracil.
Diethyl 2-methyloxalacetate	73	Benzylurea	60.0	3-benzyl-5-methyluracil.
Diethyl 2-butyloxalacetate	89.5	β -Phenethylthiourea	72.0	3-(β -phenethyl)-5-buty-2-thiouacil.
Diethyl 2-methyloxalacetate	73	2-indanylurea	74.8	3-(3-indanyl)-5-methyluracil.
Diethyl 2-ethyloxalacetate	78.5	3,4-dichlorophenylurea	82.0	3-(3,4-dichlorophenyl)-5-ethyluracil.
Diethyl 2-propyloxalacetate	84	3-nitro-4-chlorophenylthiourea	92.3	3-(3-nitro-4-chlorophenyl)-5-propyl-2-thiouacil.
Diethyl 2-ethoxyoxalacetate	93	Ethylthiourea	41.6	3-ethyl-5-ethoxy-2-thiouacil.
Diethyl 2-methoxyoxalacetate	87	Butylurea	46.3	3-buty-5-methoxyuracil.
Diethyl 2-propoxyoxalacetate	98	Octylurea	68.7	3-octyl-5-propoxyuracil.
Diethyl 2-methyloxalacetate	73	Norbornenyl urea	62.3	3-norbornenyl-5-methyluracil.
Diethyl 2-butoxyoxalacetate	104	m-Tolylurea	60.0	3-m-tolyl-5-butoxyuracil.
Diethyl 2-methyloxalacetate	73	(3a,4,5,6,7,7a-hexahydro-4,7-methano-5-indanyl)urea	79.8	3-(3a,4,5,6,7,7a-hexahydro-4,7-methano-5-indanyl)-5-methyluracil.
Do	73	1-(decahydro-1,4,5,8-dimethano-naphth-2-yl)urea	88.4	3-(decahydro-1,4,5,8-dimethanonaphth-2-ylmethyl)-5-methyluracil.
Do	73	1-(norbornylmethyl)urea	67.2	3-(norbornylmethyl)-5-methyluracil.
Diethyl 2-methoxyoxalacetate	87	p-Anisylurea	66.8	3-(p-anisyl)-5-methoxyuracil.
Do	114	Bornylurea	61.2	3-bornyl-5-methoxyuracil.
Do	87	Cyclohexylurea	57	3-cyclohexyl-5-methoxyuracil.
Diethyl 2-fluorooxalacetate	74.1	do	57	3-cyclohexyl-5-fluorouracil.
Do	74.1	γ -Decahydronaphthylurea	78.4	3-(γ -decahydronaphthyl)-5-fluorouracil.
Do	74.1	Cyclohexylthiourea	63	3-cyclohexyl-5-fluoro-2-thiouacil.
Do	74.1	Cycloheptylurea	62.5	3-cycloheptyl-5-fluorouracil.
Do	74.1	Sec.-butylurea	47	3-sec.-butyl-5-fluorouracil.
Do	74.1	Bicyclo[2.2.2]oct-2-ylurea	67.2	3-bicyclo[2.2.2]oct-2-yl-5-fluorouracil.
Do	74.1	Isopropylurea	41	3-isopropyl-5-fluorouracil.
Do	74.1	Phenylurea	54.4	3-phenyl-5-fluorouracil.
Do	74.1	Norbornylurea	62	3-norbornyl-5-fluorouracil.
Diethyl 2-methyloxalacetate	73	Allylurea	42	3-allyl-5-methyluracil.
Do	73	Cyclopropylmethylurea	42	3-cyclopropylmethyl-5-methyluracil.
Do	73	Cyclohexylmethylurea	58.8	3-cyclohexylmethyl-5-methyluracil.
Do	73	1-(4-methylcyclohexylmethyl)urea	64.4	3-(4-methylcyclohexylmethyl)-5-methyluracil.
Diethyl 2-ethyloxalacetate	78.5	1-(1,1-dimethylpentyl)urea	63.6	3-(1,1-dimethylpentyl)-5-ethyluracil.
Diethyl 2-methyloxalacetate	73	1-(1-ethylbutyl)urea	58	3-(1-ethylbutyl)-5-methyluracil.
Do	73	Cyclocetylurea	68	3-cyclooctyl-5-methyluracil.
Do	73	Norbornylurea	62.5	3-norbornyl-5-methyluracil.
Diethyl 2-ethyloxalacetate	78.5	Cyclopentylurea	51	3-cyclopentyl-5-ethyluracil.
Diethyl 2-butyloxalacetate	89.5	Cyclohexylurea	56	3-cyclohexyl-5-butyluracil.
Diethyl 2-methyloxalacetate	73	Cyclohexylthiourea	63	3-cyclohexyl-5-methyl-2-thiouacil.
Diethyl 2-cyanooxalacetate	78	Cyclohexylurea	57	3-cyclohexyl-5-cyanouracil.
Diethyl 2-methyloxalacetate	73	Cyclopropylurea	41	3-cyclopropyl-5-methyluracil.
Diethyl 2-(2-butenyl) oxalacetate	86	Isopropylurea	41	3-isopropyl-5-(2-butenyl)uracil.
Diethyl 2-allyloxalacetate	82	Cyclopentylurea	51	3-cyclopentyl-5-allyluracil.
Diethyl 2-methyloxalacetate	73	Isopropylurea	41	3-isopropyl-5-methyluracil.
Do	73	Sec.-butylurea	47	3-sec.-butyl-5-methyluracil.
Do	73	Fenethylurea	29.6	3-fenethyl-5-methyluracil.
Diethyl 2-ethyloxalacetate	78	Heptylthiourea	69.5	3-heptyl-5-ethyl-2-thiouacil.
Diethyl 2-methyloxalacetate	73	Decylurea	80.0	3-decyl-5-methyluracil.
Do	73	(Hexahydroindan-5-ylmethyl)urea	78.5	3-(hexahydroindan-5-ylmethyl)-5-methyluracil.
Do	73	4-bromocyclohexylmethylmethylurea	94.0	3-(4-bromocyclohexylmethyl)-5-methyluracil.
Diethyloxalacetate	75.2	Bornylurea	78.4	3-bornyluracil.
Do	75.2	Fenethylurea	78.4	3-fenethyluracil.
Do	75.2	3-(3-cyclohexen-1-ylmethyl)urea	61.6	3-(3-cyclohexen-1-ylmethyl)uracil.
Do	75.2	3-(4-methoxy-3-cyclohexen-1-ylmethyl)urea	73.6	3-(4-methoxy-3-cyclohexen-1-ylmethyl)uracil.
Do	75.2	3-propyl-2-norcamphanylurea	78.4	3-(3-propyl-2-norcamphanyl)uracil.
Do	75.2	Norbornenylurea	61.8	3-norbornenyluracil.
Do	75.2	Norbornylurea	62.0	3-norbornyluracil.
Do	75.2	γ -Decahydronaphthylurea	78.4	3-(γ -Decahydronaphthyl)uracil.
Do	75.2	3a,4,5,6,7,7a-hexahydro-4,7-methano-5-indanylurea	78.0	3-(3a,4,5,6,7,7a-hexahydro-4,7-methano-5-indanyl)uracil.
Do	75.2	3a,4,5,6,7,7a-hexahydro-4,7-methano-5-indanylurea	78.5	3-(3a,4,5,6,7,7a-hexahydro-4,7-methano-5-indanyl)uracil.
Do	75.2	(2,3-dichloro-3a,4,5,6,7,7a-hexahydro-4,7-methano-5-indanyl)urea	106.0	3-(2,3-dichloro-3a,4,5,6,7,7a-hexahydro-4,7-methano-5-indanyl)uracil.

EXAMPLE 2.—PREPARATION OF 3-CYCLOHEXYL-5-BROMOURACIL

Seventeen parts by weight of bromine are added over a 20-minute period to a stirred solution of 19.4 parts by weight of 3-cyclohexyluracil in 100 parts by weight of glacial acetic acid. The temperature is maintained below 30° C. during the addition. The solution is stirred at 20–30° C. for an additional 1½ hours and is then poured into 2 volumes of ice water with stirring, whereupon a white solid separates. This solid is filtered, washed with water until acid-free, and dried to give essentially pure 3-cyclohexyl-5-bromouracil.

The following compounds are prepared as in Example 2 by substituting equivalent amounts of the 3-substituted uracils and halogens set forth in the following table for 15 the 3-cyclohexyluracil and bromine:

of the listed 3-substituted uracil starting reactants for the 3-butyluracil:

5	Uracil starting reactant	5-nitouracil product
	3-cyclohexyluracil	3-cyclohexyl-5-nitouracil
	3-isopropyluracil	3-isopropyl-5-nitouracil
	3-sec.-amyluracil	3-sec.-amyl-5-nitouracil
	3-(3-nitro-4-chlorophenyl) uracil	3-(3-nitro-4-chlorophenyl)-5-nitouracil
10	3-allyluracil	3-allyl-5-nitouracil
	3-sec.-butyluracil	3-sec.-butyl-5-nitouracil
	3-cyclooctyluracil	3-cyclooctyl-5-nitouracil
	3-cyclobutyluracil	3-cyclobutyl-5-nitouracil
	3-cyclopentenyluracil	3-cyclopentenyl-5-nitouracil
	3-fenethyluracil	3-fenethyl-5-nitouracil
	3-norbornyluracil	3-norbornyl-5-nitouracil

Uracil starting reactant	Parts by weight	Halogen	Parts by weight	Uracil product
3-m-chlorophenyluracil	22.3	Cl	8.0	3-(m-chlorophenyl)-5-chlorouracil.
3-cyclohexyluracil	19.4	Br	17.0	3-cyclohexyl-5-bromouracil.
3-(3-hydroxypropyl)uracil	16.0	Cl	8.0	3-(3-hydroxypropyl)-5-chlorouracil.
3-cyclopentyluracil	18.0	Br	17.0	3-cyclopentyl-5-bromouracil.
3-cyclooctyluracil	22.2	Cl	8.0	3-cyclooctyl-5-chlorouracil.
3-(2-hydroxyethyl)uracil	14.0	Br	17.0	3-(2-hydroxyethyl)-5-bromouracil.
3-cyclopentenyluracil	17.8	Cl	8.0	3-cyclopentenyl-5-chlorouracil.
3-(3-ethoxypropyl)uracil	18.7	Br	17.0	3-(3-ethoxypropyl)-5-bromouracil.
3-(p-bromophenyl)uracil	26.7	Cl	8.0	3-(p-bromophenyl)-5-chlorouracil.
3-isopropyluracil	15.4	Br	17.0	3-isopropyl-5-bromouracil.
3-hexyluracil	19.7	Cl	8.0	3-hexyl-5-chlorouracil.
3-phenyluracil	18.8	Br	17.0	3-phenyl-5-bromouracil.
3-(3,4-dichlorophenyl)uracil	25.9	Br	17.0	3-(3,4-dichlorophenyl)-5-bromouracil.
3-tert.-butyluracil	15.3	Br	17.0	3-tert.-butyl-5-bromouracil.
3-cyanouracil	13.7	Br	17.0	3-cyano-5-bromouracil.
3-dimethylaminouracil	15.5	Br	17.0	3-dimethylamino-5-bromouracil.
3-methoxyuracil	14.0	Br	17.0	3-methoxy-5-bromouracil.
3-ethyluracil	14.0	Cl	8.0	3-ethyl-5-chlorouracil.
3-(3-methoxypropyl)uracil	17.4	Br	17.0	3-(3-methoxypropyl)-5-bromouracil.
3-sec.-amyluracil	18.2	Br	17.0	3-sec.-amyl-5-bromouracil.
3-allyluracil	15.2	Cl	8.0	3-allyl-5-chlorouracil.
3- α -naphthyluracil	24.0	Br	17.0	3- α -naphthyl-5-bromouracil.
3-decytluracil	25.2	Br	17.0	3-decytl-5-bromouracil.
3-(2-chloroethyl)uracil	17.6	Cl	8.0	3-(2-chloroethyl)-5-chlorouracil.
3-(9-deceny)uracil	25.0	Br	17.0	3-(9-deceny)-5-bromouracil.
3-(9-deceny)uracil	25.0	Br	51.0	3-(9,10-dibromodecyl)-5-bromouracil.
3-(3,4,5-trichlorophenyl)uracil	29.1	Cl	8.0	3-(3,4,5-trichlorophenyl)-5-chlorouracil.
3-(bicyclo[2.2.2]oct-5-en-2-yl)uracil	21.8	Br	17.0	3-(bicyclo[2.2.2]oct-5-en-2-yl)-5-bromouracil.
3-(1,2-dimethylcyclopentyl)uracil	20.8	Br	17.0	3-(1,2-dimethylcyclopentyl)uracil.
3-fenethyluracil	24.8	Cl	8.0	3-fenethyl-5-chlorouracil.
3-(chloronorbornyl)uracil	24.1	Br	17.0	3-(chloronorbornyl)-5-bromouracil.
3-norbornenyluracil	20.4	Br	17.0	3-norbornenyl-5-bromouracil.
3-(6-methoxy-3,3-dimethyl-indanyl)uracil	28.5	Cl	8.0	3-(6-methoxy-3,3-dimethylindanyl)-5-chlorouracil.
3-(1,4,5,6-tetrachloro-7,7-dimethoxybicyclo[2.2.1]hept-5-en-2-ylmethyl)uracil	30.5	Cl	8.0	3-(1,4,5,6-tetrachloro-7,7-dimethoxybicyclo[2.2.1]hept-5-en-2-ylmethyl)-5-chlorouracil.
3-(5,6,7,8,10,10-hexachloro-1,2,3,4,4a,5,8,8a-octahydro-1,4,5,8-dimethano-2-naphthyl)uracil	47.7	Cl	8.0	3-(5,6,7,8,10,10-hexachloro-1,2,3,4,4a,5,8,8a-octahydro-1,4,5,8-dimethano-2-naphthyl)-5-chlorouracil.
3-(3,4-dimethylcyclohexyl)uracil	21.6	Cl	8.0	3-(3,4-dimethylcyclohexyl)-5-chlorouracil.
3-(3a,4,5,6,7,7a-hexahydro-4,7-methano-5-indanyl)uracil	24.5	Br	17.0	3-(3a,4,5,6,7,7a-hexahydro-4,7-methano-5-indanyl)-5-bromouracil.
3-(γ -1,2,3,4-tetrahydronaphthyl)uracil	24.2	Cl	8.0	3-(γ -1,2,3,4-tetrahydronaphthyl)-5-chlorouracil.
3-(1,2,3,4,4a,5,6,7,8,8a-decahydronaphth-6-yl)uracil	26.1	Br	17.0	3-(1,2,3,4,4a,5,6,7,8,8a-decahydronaphthyl)-5-bromouracil.
3-(4-bromocyclohexyl)uracil	27.3	Br	17.0	3-(4-bromocyclohexyl)-5-bromouracil.
3-(5,6,7,8-tetrahydronaphthyl)uracil	23.1	Br	17.0	3-(5,6,7,8-tetrahydronaphthyl)-5-bromouracil.

EXAMPLE 3.—PREPARATION OF 3-BUTYL-5-NITROURACIL

A solution of 40 parts by volume of fuming nitric acid and 40 parts by volume of fuming sulfuric acid (20% SO_3) is stirred at 25–30° C. while 18.4 parts by weight of 3-butyluracil are added portionwise over a 30-minute period. The entire reaction mixture is stirred an additional 30 minutes, then poured slowly into 4 volumes of stirred ice water. The desired product separates out as a pale yellow solid. It is collected by filtration, washed well with water, and air-dried.

The following 5-nitro substituted uracils can be prepared as in Example 3 by substituting equivalent amounts

EXAMPLE 4.—PREPARATION OF 3-CYCLOHEXYL-5-THIOCYANO-2-THIOURACIL

A vigorously stirred suspension of 39 parts by weight of lead thiocyanate in 200 parts by volume of carbon tetrachloride is slowly diluted with 17.6 parts by weight of bromine. Occasional external cooling is required to hold the temperature of the reaction mixture at 15–20° C. At the end of the addition, stirring is continued until the bromine color is discharged, after which the solution is filtered rapidly under anhydrous conditions. To this solution is added 19.4 parts by weight of 3-cyclohexyluracil, and the resulting mixture is stirred at room temperature for 5 hours. At the end of this time the

solvent is removed, leaving essentially pure 3-cyclohexyl-5-thiocyanouracil as a solid residue.

The following compounds can be prepared as in Example 4 by substituting equivalent amounts of the appropriate uracil starting reactants for the 3-cyclohexyluracil:

- 3-isopropyl-5-thiocyanouracil
- 3-(10-methoxycarbonyldecyl)-5-thiocyanouracil
- 3-allyl-5-thiocyanouracil
- 3-(ethoxycarbonylmethyl)-5-thiocyanouracil
- 3-(m-pyridyl)-5-thiocyanouracil
- 3-sec.-butyl-5-thiocyanouracil
- 3-(1,1,5,5-tetramethyl-5-hydroxypentyl)-5-thiocyanouracil
- 3-(m-nitrophenyl)-5-thiocyanouracil
- 3-cyclopropyl-5-thiocyanouracil
- 3-cyano-5-thiocyanouracil
- 3-bornyl-5-thiocyanouracil
- 3-(2-indanyl)-5-thiocyanouracil
- 3-cyclohexyl-5-thiocyanouracil

EXAMPLE 5.—PREPARATION OF 3-TERT.-BUTYL-5-THIOCYANOURACIL

A mixture of 182 parts of 3-tert.-butyluracil, 700 parts of acetic acid and 152 parts of ammonium thiocyanate is stirred at 10–15° C. as 160 parts of bromine, dissolved in 180 parts of acetic acid, are gradually added over a period of 2 to 4 hours. When the addition is complete, the mixture is stirred for a short time at 15° C. to insure completion, and then diluted with 9000 parts of ice and water.

The mixture is then extracted with 4000 parts of dichloromethane. The organic layer is separated, filtered free of polymeric material, washed with sodium bicarbonate solution, dried over magnesium sulfate, filtered, and concentrated to dryness at reduced pressure.

The resulting 3-tert.-butyl-5-thiocyanouracil can be recrystallized from such solvents as nitromethane or 1,1,2-trichloroethane.

EXAMPLE 6.—PREPARATION OF 3-SEC.-BUTYL-5-CYANOURACIL

A mixture of 116 parts of sec.-butylurea, 66 parts of malononitrile and 444 parts of triethyl orthoformate is heated at 70–100° C. for 3 hours with stirring. The volatile constituents are distilled off at reduced pressure at steam-bath temperature. The resulting solid, [(3-sec.-butylureido)methylene]malononitrile is purified by recrystallizing from a mixture of alcohol and water.

One hundred and ninety-two parts of [(3-sec.-butylureido)methylene]malononitrile, 54 parts of sodium methoxide and 1000 parts of methanol are stirred, protected from atmospheric moisture, and allowed to stand for 5 days at room temperature. The alcohol is removed by distillation at reduced pressure, and the resulting solid is dissolved in 2000 parts of cold water. The solution is made slightly acidic by the gradual addition of acetic acid, and the 3-sec.-butyl-5-cyanocytosine which separates is filtered off, washed with 1000 parts of cold water and dried.

A solution of 192 parts of 3-sec.-butyl-5-cyanocytosine in 1000 parts of 3 N hydrochloric acid is refluxed for 3 hours and then cooled. The 3-sec.-butyl-5-cyanouracil which separates is filtered off and recrystallized from a mixture of alcohol and water.

The 5-cyano substituted uracils listed in the following table can be prepared in a similar fashion by substituting equivalent amounts of suitably substituted ureas for 3-sec.-butylurea:

- 3-isopropyl-5-cyanouracil
- 3-tert.-butyl-5-cyanouracil
- 3-(3a,4,5,6,7,7a-hexahydro-4,7-methano-5-indanyl)-5-cyanouracil
- 3-norbornenylmethyl-5-cyanouracil
- 3-fenchyl-5-cyanouracil

EXAMPLE 7.—PREPARATION OF 3-CYCLOHEXYL-5-IODOURACIL

A mixture of 194 parts of 3-cyclohexyluracil, 1000 parts of acetic acid, and 253 parts of iodine is stirred at 100° C. as 72 parts of fuming nitric acid are gradually added. When the addition is complete, the dark colored solution is refluxed for about one-half hour and then cooled to ice-bath temperature.

The excess iodine which precipitates is filtered off and the filtrate is diluted with 4000 parts by weight of cold water. The iodine remaining in solution is reduced to iodide ion by adding a saturated solution of sodium bisulfite until the solution becomes colorless.

The aqueous solution is extracted with 6000 parts by weight of methylene chloride, the organic layer is separated, washed with saturated sodium bicarbonate solution and distilled under reduced pressure to give solvent-free, essentially pure 3-cyclohexyl-5-iodouracil.

The uracils in the following table can be similarly prepared by substituting equivalent amounts of properly 3-substituted uracils for 3-cyclohexyluracil:

- 3-bornyl-5-iodouracil
- 3-cyclopropyl-5-iodouracil
- 3-cyclobutyl-5-iodouracil
- 3-cyclopentyl-5-iodouracil
- 3-sec.-butyl-5-iodouracil
- 3-isopropyl-5-iodouracil
- 3-ethyl-5-iodouracil
- 3-norbornyl-5-iodouracil
- 3-decahydronaphthyl-5-iodouracil

EXAMPLE 8.—PREPARATION OF 3-CYCLOHEXYL-5-HYDROXYMETHYLURACIL

A mixture of 19.4 parts by weight of 3-cyclohexyluracil, 140 parts by weight of water, 31.5 parts by weight of ethyl alcohol, 6.6 parts by weight of paraformaldehyde, and 2.0 parts by weight of barium hydroxide is heated until all the components are in solution. The mixture is then cooled and the oil which precipitates is extracted with ethyl ether. The ether extract is dried over magnesium sulfate, filtered, and concentrated at reduced pressure to a slightly gummy solid. This solid is recrystallized from acetonitrile to give 3-cyclohexyl-5-hydroxymethyluracil.

The following compounds are prepared as in Example 8 by substituting equivalent amounts of other suitable uracil reactants for cyclohexylurea:

- 3-(m-fluorophenyl)-5-hydroxymethyluracil
- 3-tert.-octyl-5-hydroxymethyluracil
- 3-phenyl-5-hydroxymethyluracil
- 3-(5-cyanopentyl)-5-hydroxymethyluracil
- 3-cyclopentyl-5-hydroxymethyluracil
- 3-(2-cyanoethyl)-5-hydroxymethyluracil
- 3-(2-buten-3-yl)-5-hydroxymethyluracil
- 3-(5,6,7,8,9,9-hexachloro-1,2,3,4,4a,5,6,7,8,8a-decahydro-5,8-methanaphth-2-ylmethyl)-5-hydroxyuracil
- 3-norbornyl-5-hydroxymethyluracil
- 3-o-methylcyclohexyl-5-hydroxymethyluracil
- 3-(3a,4,5,6,7,7a-hexahydro-4,7-methano-5-indenyl)-5-hydroxymethyluracil
- 3-(3a,4,5,6,7,7a-hexahydro-4,7-methano-5-indenyl)-5-hydroxymethyluracil
- 3-(2,3-dichloro-3a,4,5,6,7,7a-hexahydro-4,7-methano-5-indenyl)-5-hydroxymethyluracil
- 3-(γ -decahydronaphthyl)-5-hydroxymethyluracil
- 3-(γ -1,2,3,4-tetrahydronaphthyl)-5-hydroxymethyluracil
- 3-(6-methoxy-3,3-dimethylindanyl)-5-hydroxymethyluracil
- 3-(5,6,7,8,10,10-hexachloro-1,2,3,4,4a,5,8,8a-octahydro-1,4,5,8-dimethano-2-naphthyl)-5-hydroxymethyluracil
- 3-(3-propyl-2-norcamphanyl)-5-hydroxymethyluracil
- 3-(4-methoxy-3-cyclohexen-1-ylmethyl)-5-hydroxymethyluracil
- 3-fenchyl-5-hydroxymethyluracil
- 3-bornyl-5-hydroxymethyluracil
- 3-(4-bromocyclohexyl)-5-hydroxymethyluracil

EXAMPLE 9.—PREPARATION OF 3-ISOPROPYL-5-CHLOROMETHYLURACIL

A combination of 15.4 parts by weight of 3-isopropyluracil and 38 parts by weight of chloromethylmethyl ether is heated in an autoclave under endogenous pressure at 100° C. for 25 hours. The material is cooled and the excess reagent evaporated under vacuum. The product is extracted from the residue with dry dioxane. The dioxane is then evaporated to dryness, leaving essentially pure 5-chloromethyl-3-isopropyluracil as a residue.

EXAMPLE 10.—PREPARATION OF 5-CHLOROMETHYL-3-NORBORNYLURACIL

To 452 parts of rapidly stirred thionyl chloride, maintained at 20–25° C. with an ice bath, are gradually added 206 parts of 5-hydroxymethyl-3-norbornyluracil. Caution is used in carrying out this reaction because of the large amounts of acidic gases produced and the vigor of the reaction.

A condenser is used to retain the thionyl chloride reactant, and a scrubber washes away the gases evolved in the reaction.

When the uracil is dissolved, the solution is distilled to dryness at reduced pressure at 50° C. The solid is triturated with 200 parts of a 1:1 mixture of 1,1,2-trichloroethane and heptane, and filtered.

The resulting solid 5-chloromethyl-3-norbornyluracil can be recrystallized from nitromethane or 1,1,2-trichloroethane.

The following 5-halomethyluracils can be prepared by the methods of Examples 9 or 10 by substituting an appropriate uracil for the 3-isopropyluracil of Example 9, or by substituting an appropriate thionyl halide for the thionyl chloride of Example 10.

- 3-(2-bromoethyl)-5-chloromethyluracil
- 3-(2,4,5-trichlorophenyl)-5-chloromethyluracil
- 3-(p-methoxybenzyl)-5-chloromethyluracil
- 3-(3-chloro-4-isopropylphenyl)-5-chloromethyluracil
- 3-butyl-5-chloromethyluracil
- 3-(dimethylaminopropyl)-5-chloromethyluracil
- 3-cyclohexyl-5-bromomethyluracil
- 3-sec.-butyl-5-bromomethyluracil
- 3-sec.-butyl-5-fluoromethyluracil
- 3-cyclohexyl-5-fluoromethyluracil

EXAMPLE 11.—PREPARATION OF 3-CYCLOHEXYL-5-METHOXYSYMMETHYLURACIL

Five hundred parts of methanol, ten parts of chloroacetic acid, and 225 parts of 3-cyclohexyl-5-hydroxymethyluracil are charged into a bomb and heated at 125° C. for 5 hours. The reaction mixture is then concentrated to an oil, which is taken up in 400 parts of acetonitrile, refluxed for a short time with 5 parts of decolorizing carbon, filtered hot and distilled under reduced pressure to yield solvent-free 3-cyclohexyl-5-methoxymethyluracil.

The uracils in the following list can be prepared in a similar fashion by substituting equivalent amounts of appropriately substituted uracils and alcohols for 3-cyclohexyl-5-hydroxymethyluracil and methanol:

- 3-norbornenyl-5-methoxymethyluracil
- 3-cyclohexyl-5-butoxymethyluracil
- 3-norbornenylmethyl-5-ethoxymethyluracil
- 3-norbornyl-5-propoxymethyluracil
- 3-bornyl-5-methoxymethyluracil
- 3-(3a,4,5,6,7,7a-hexahydro-4,7-methano-5-indenyl)-5-methoxymethyluracil
- 3-(3a,4,5,6,7,7a-hexahydro-4,7-methano-5-indenyl)-5-methoxymethyluracil
- 3-decahydronaphthyl-5-methoxymethyluracil
- 3-(tert.-octyl)-5-methoxymethyluracil

EXAMPLE 12.—PREPARATION OF 3-(3-METHYLCYCLOHEXYL)-5-METHYLTHIOMETHYLURACIL

An autoclave is charged with 238 parts of 5-hydroxymethyl-3-(3-methylcyclohexyl)uracil, 1500 parts of methanol and 50 parts of methyl mercaptan. The mixture is

shaken and heated at 125° C. for 5 hours. It is then cooled and poured into 7000 parts of ice and water.

The white solid which precipitates is filtered off and recrystallized from acetonitrile or nitromethane, giving

- 5 pure 3-(3-methylcyclohexyl)-5-methylthiomethyluracil.
10 The compounds in the following table are similarly prepared by substituting equivalent amounts of the appropriate substituted uracils and equivalent amounts of methyl mercaptan, thiophenol, thioacetic acid or hydrogen sulfide for the 5-hydroxymethyl-3-(3-methylcyclohexyl)uracil and methyl mercaptan:

- 3-cyclopropyl-5-methylthiomethyluracil
- 3-cyclohexyl-5-thiolmethyleruracil
- 15 3-(3-chlorophenyl)-5-methylthiomethyluracil
- 3-(3-trifluoromethylphenyl)-5-thiolmethyleruracil
- 3-(3-chloro-4-butoxyphenyl)-5-phenylthiomethyluracil
- 3-(3,5-dichloro-4-nitrophenyl)-5-thiolmethyleruracil
- 3-(4-sec.-amylphenyl)-5-methylthiomethyluracil
- 20 3-(m-tolyl)-5-methylthiomethyluracil
- 3-(carvacryl)-5-thiolmethyleruracil
- 3(3,4-dimethylbenzyl)-5-thiolmethyleruracil
- 3-(p-nitrobenzyl)-5-thiolmethyleruracil
- 3-(p-ethylbenzyl)-5-methylthiomethyluracil
- 25 3-(2,5-dichlorobenzyl)-5-thiolmethyleruracil
- 3-(4-isopropoxybenzyl)-5-methylthiomethyluracil
- 3-(3,5-dibromophenyl)-5-thiolmethyleruracil
- 3-(3-propoxymethyl)-5-thiolmethyleruracil
- 3-tert.-butyl-5-thiolmethyleruracil
- 30 3-cyano-5-methoxycarbonylthiomethyluracil
- 3-(bicyclo[3.2.1]oct-3-yl)-5-methylthiomethyluracil
- 3-(5,6,7,8,10,10-hexachlorodecahydro-1,4,5,8-dimethano-2-naphthyl)-5-thiolmethyleruracil

EXAMPLE 13.—PREPARATION OF 3-BUTYL-5-CHLOROURACIL, SODIUM SALT

A solution of 4 parts by weight of sodium hydroxide in 100 parts of water is treated with 20.3 parts by weight of 3-butyl-5-chlorouracil. Stirring and warming is employed to effect solution. Water is removed under reduced pressure, leaving 3-butyl-5-chlorouracil, sodium salt as a white residue.

EXAMPLE 14.—PREPARATION OF TETRABUTYLYLAMMONIUM SALT OF 3-n-BUTYL-5-METHYLURACIL

- 45 One hundred eighty-two parts of 3-n-butyl-5-methyluracil are gradually added, with stirring, to 835 parts of a one-molar solution of tetrabutylammonium hydroxide in methanol. When solution is complete, the solvent is distilled off at reduced pressure. The white solid tetrabutylammonium salt of 3-n-butyl-5-methyluracil which remains is sufficiently pure for incorporation into herbicidal formulations.

EXAMPLE 15.—PREPARATION OF A 1:1 COMPLEX OF 5-BROMO-3-INDANYLURACIL AND PENTACHLOROPHENOL

A dry mixture of 307 parts of 5-bromo-3-indanyluracil and 266 parts of pentachlorophenol is gradually heated until a clear melt results. It is stirred for a short time to insure complex formation, and then cooled. The resulting solid cake can be recrystallized from nitromethane.

EXAMPLE 16.—PREPARATION OF THE 2:1 COMPLEX OF 5-BROMO-3-SEC.-BUTYLURACIL AND p-METHOXYPHENOL

A mixture of 247 parts of 5-bromo-3-sec.-butyluracil, 62 parts of p-methoxyphenol and 600 parts of nitromethane is stirred and heated until the components are dissolved. Ten parts of decolorizing charcoal are added, and the mixture is stirred for a short time and then filtered.

The filtrate is chilled to ice-bath temperature, and the pure, solid 2:1 complex of 5-bromo-3-sec.-butyluracil and p-methoxyphenol is filtered off and dried.

EXAMPLE 17.—PREPARATION OF THE ETHYLENEDI-AMINE ADDITION COMPOUND OF 5-BROMO-3-ISOPROPYLURACIL

A mixture of 233 parts of 5-bromo-3-isopropyluracil in sufficient acetonitrile to form a concentrated solution at room temperature is stirred as 60 parts of ethylenediamine are gradually added.

The solid pure addition compound of 5-bromo-3-isopropyluracil and ethylenediamine which precipitates is filtered off.

EXAMPLE 18.—PREPARATION OF THE ETHANOL-AMINE ADDITION COMPOUND OF 3-CYCLOHEXYL-5-METHYLURACIL

A mixture of 208 parts of 3-cyclohexyl-5-methyluracil and 61 parts of ethanolamine is gradually heated. The resulting liquid is stirred to assure even distribution of the two components, and is then allowed to cool and solidify.

The resulting solid addition compound is sufficiently pure for incorporation into herbicidal formulations. If desired, it may be purified by recrystallization from such solvents as acetonitrile or nitromethane.

HERBICIDAL COMPOSITIONS

Liquid formulations

EXAMPLE 19.—AQUEOUS SOLUTION

	Percent
3-tert.-butyl-5-chlorouracil, Na salt	20
Sodium lauryl sulfate	2
Water	78

These components are prepared as a concentrated aqueous solution by dissolving the two soluble salts in the water, with agitation.

Other soluble salts suitable for preparation of water concentrates are

3-(decahydro-1,4,5,8-dimethanonaphthyl)-5-methyluracil, Na salt	
3-phenyl-5-thiocyanato-2-thiouracil, Li salt	
3-butyl-5-cyanouracil, Na salt	
3-cyclohexyluracil, Na salt	
3-fenchyluracil, Na salt	
3-(1-ethylhexyl)-5-methyluracil, K salt	
3-(1,1-dimethylbutyl)-5-methyluracil, K salt	

The aqueous solution of 3-(tert.-butyl)-5-chlorouracil, sodium salt, is used for directed post-emergence weed control in gladiolus beds. A concentration of one pound of active ingredient per acre in 30 gallons of water gives excellent control of seedling weeds such as crab grass, pigweed, violet weed, and flower-of-an-hour. Care must be taken to direct the spray so as to avoid contact with the gladiola plants.

At concentrations of 15 to 25 pounds per acre in 80 gallons of water, all of the above compositions give excellent control of a wide variety of annual grasses and broadleaf weeds growing on railroad ballast.

EXAMPLE 20.—SOLUTION

	Percent
3-butyl-5-methyluracil, 2:1 complex with phenol	20
Isophorone	54
Alkylated naphthalene	20
Blend of polyoxyethylene ethers and oil soluble sulfonates	6

These ingredients are mixed with 80 gallons of water and applied at a rate of 10-15 pounds of the active compound (2:1 complex) per acre. Excellent kill of weeds, followed by good residual weed control, is obtained on a mixed population of weeds containing quack grass, barnyard grass, crabgrass, seedling Johnson grass, volunteer wheat, pigweed, velvetleaf, and lamb's quarters.

EXAMPLE 21.—WATER SUSPENSION

A water suspension is prepared by grinding the following ingredients together in a ball or roller mill until

the solids are finely dispersed in the water and the average particle size is less than 5 microns:

	Percent
3-fenchyl-5-methyluracil	25
Hydrated attapulgite	2
Lignin sulfonic acids, Na sodium salt	5
Water	68

EXAMPLE 22.—WATER SUSPENSION

A water suspension is prepared by grinding the following ingredients together in a ball or roller mill:

	Percent
3-isopropyl-5-bromouracil	25
Hydrated attapulgite	2
Lignin sulfonic acid, Na salt	5
Water	68

Grinding is continued until the particles in the suspension have been reduced to diameters of less than 5 microns.

The water suspensions of Examples 23 and 24 control seedling brush growing along fence rows. An application of the suspensions with a pressure sprayer at concentrations of 10 to 20 pounds of active ingredient per acre in 120 gallons of water controls oak and willow seedlings.

EXAMPLE 23.—OIL SUSPENSION

An oil suspension is prepared by grinding the following ingredients together in a ball or roller mill until the solids are finely dispersed in the oil and the average particle size is less than 5 microns:

	Percent
3-benzyl-5-chlorouracil	25
Soya lecithin	5
Aliphatic hydrocarbon oil	70

This oil suspension is applied in 50 gallons of water as an over-all spray on a stand of established quack grass, using a concentration of 16 pounds of active ingredient per acre. Excellent control is obtained. A check of the rhizomes shows severe injury.

EXAMPLE 24.—OIL SUSPENSION

An oil suspension is prepared by grinding the following ingredients together in a ball or roller mill until the solids are finely dispersed in the oil and the average particle size of the active ingredient is less than 5 microns:

	Percent
3-(p-cumyl)-5-thiocyanouracil	25
Diesel oil	67

Polyoxyethylene sorbitan ester of mixed rosin and fatty acids

This oil suspension is diluted with water to form a water emulsion and is applied, at a concentration of 2-4 pounds of active ingredient per acre, as a directed spray to grasses growing in sugar cane. This treatment gives excellent control of mixed annual grasses and broad-leaves.

EXAMPLE 25.—OIL SUSPENSION

The following ingredients are used to prepare an oil suspension:

	Percent
3-(p-tolyl)-5-methyluracil	15
Diesel oil	80

Polyoxyethylene sorbitan esters of mixed rosin and fatty acids

The ingredients are ground together in a ball or roller mill until the solids are finely dispersed in the oil and the average particle size of the active ingredient is less than 5 microns. This oil suspension is diluted with water to form a water emulsion for application to plants.

3 - (4 - isopropylcyclohexylmethyl)-5-bromouracil, 3-(α, α, α - trifluoro - m-tolyl)-5-methyluracil, 3-(4-methylcy-

cylohexylmethyl)-5-methyluracil, 3-cyclohexyl-5-bromouracil and 3-cyclopentenyl-5-bromouracil are prepared as oil suspensions in a similar manner.

The emulsifiable oils of Examples 25, 26 and 27 are useful for weed control in railroad yards and cattle yards. When any of these compositions are diluted with water at a rate of 160 gallons per acre and sprayed from a railroad spray car at a level of about 25 pounds of active material per acre, vegetation such as quack grass, crabgrass, seedling Johnson grass, seedling Bermuda grass, brome grass, ragweed, cocklebur, lamb's-quarter, and mare's-tail is controlled for an extended period.

These same oil suspension compositions, when applied to a drainage ditch infested with mixed annual and perennial broadleaf and grass weeds at concentrations of 25 pounds of active material per acre in 150 gallons of water, also give excellent control of vegetation. The ditch remains bare for an extended period.

EXAMPLE 26.—SOLUTION

A mixture of 40 parts of 5-bromo-3-isopropyluracil and 60 parts of ethanolamine is stirred at room temperature until a clear solution is formed.

An application of 20 pounds of this formulation per acre (active) in 60 gallons of water per acre controls young and growing cheat grass, foxtail, wild barley, barnyard grass, wild rye, crabgrass, velvet leaf and lamb's quarters growing in an outdoor storage yard.

EXAMPLE 27.—CONCENTRATE

One part of 3-butyl-5-methyluracil, one part of dodecylamine and two parts of aromatic heavy naphtha are blended to give a clear solution.

This formulation, when applied at 20 pounds (active) per acre in 80 gallons per acre of Lion Herbicidal Oil No. 6, gives excellent control of quack grass, seedling Johnson grass, brome grass and sheep sorrel growing on a railroad siding.

EXAMPLE 28.—OIL SOLUTIONS

	Percent
3-isopropyl-5-bromouracil	10.0
2,3,6-trichlorobenzoic acid	10.0
Xylene	80.0

The solid ingredients are added to the xylene and stirred at ambient temperature until they dissolve.

This solution controls deep-rooted perennial herbaceous weeds and woody vines. A solution of thirty pounds of active ingredients is diluted to 100 gallons with a herbicidal oil and sprayed on a dense tangled growth of vines and weeds along a railroad right-of-way. Good control of trumpet vine, bindweed, poison ivy, barynard grass, foxtail, ragweed, and mare's-tail is obtained.

EXAMPLE 29.—OIL DISPERSION

	Percent
3-cyclohexyl-5-methyluracil	25.00
2,4,5-trichlorophenoxyacetic acid, isoctyl ester	6.25
Paraffin oil (90% unsulfonatable residue)	68.75

The uracil and oil are mixed together and wet-milled until the particles are under 10 microns in diameter. The ester is then added to this suspension.

This formulation is extended with No. 2 fuel oil and sprayed at 20 pounds of active ingredients in 50 gallons of oil per acre around electric power poles and transformer stations. Good control of brambles, honeysuckle, goldenrod, poison ivy, pokeweed, corn cockle, panic grass, ragweed, and sow-thistle is obtained.

EXAMPLE 30.—EMULSIFIABLE CONCENTRATE

	Percent
3-butyl-5-methyluracil	20
Alkyl, aryl polyether alcohol	5
Dimethyl ketone	75

A concentrate is prepared by mixing the three components. It can be extended with water to give an emulsion.

This formulation is extended with 30 gallons of water and used in post-emergence applications at levels of 1 to 2 pounds of active ingredient per acre on young germinating annual weeds in established asparagus beds. It is applied in the spring, prior to the emergence of the asparagus spears. Good control of foxtail, lamb's quarters, pigweed and cocklebur is obtained.

Solid formulations

EXAMPLE 31.—SOLUBLE POWDER	
10	Percent
3-butyl-5-chlorouracil, sodium salt	90
Diatomaceous silica	10

A noncaking, soluble powder is prepared by blending and micropulverizing these ingredients. When the powder is placed in water in a spray tank, the active material dissolves, leaving the silica in suspension.

This soluble salt composition is used for control of mixed annual and perennial vegetation growing around oil tank installations. Concentrations to 20 to 30 pounds of active ingredient per acre in 80 gallons of water give excellent weed control for an extended period.

Other soluble uracil salts which can be prepared and used in the same manner, with good results are

25	3-cyclohexyl-5-bromouracil, potassium salt
	3-benzyl-5-thiocyanato-2-thiouracil, lithium salt
	3-allyl-5-propyluracil, sodium salt
	3-decyl-5-fluorouracil, potassium salt

EXAMPLE 32.—WATER SOLUBLE POWDER	
30	Percent
3-butyl-5-methyluracil	50.0
Trisodium phosphate (anhydrous)	42.5
Sodium lignin sulfonate	5.0
Sodium lauryl sulfate	2.5

These ingredients are blended until homogeneous, micropulverized until the particles are 50 microns or less in diameter, and then reblended.

Equivalent amounts of other basic salts such as sodium metaborate or hydrates of trisodium phosphate may be used in this formulation in place of the anhydrous trisodium phosphate.

When applied at the rate of 4 to 6 pounds (active) per acre in 40 gallons of water, this formulation controls such annual and seedling perennial grasses as Johnson grass, giant foxtail, barnyard grass, crab grass, cheat, wild barley, pigweed and lamb's quarters growing along a roadside.

EXAMPLE 33.—PELLETS

	Percent
50	3-butyl-5-bromouracil
	Alkyl naphthalene sulfonic acid, Na salt
	Anhydrous sodium sulfate
	Non-swelling clay

This composition is blended and micropulverized, then mixed with 15-20% water and extruded under pressure through an orifice to produce rods which are cut into pellets and dried.

EXAMPLE 34.—PELLETS

	Parts
60	3-propynyl-5-bromouracil
	Water
	Hide glue (20% aqueous)
	Glass frits (20-30 mesh)

The active ingredient is first made into an aqueous suspension by ball milling with the water and hide glue. The aqueous suspension is then sprayed onto the glass frits with continuous agitation in a ribbon blender. When complete coverage is obtained, the frits are removed and dried in a tunnel drier.

EXAMPLE 35.—PELLETS (FAST RELEASE)

	Percent
75	3-allyl-5-fluorouracil
	Non-swelling Ca, Mg bentonite

This mixture is first blended, then micropulverized. The product is moistened with 20-23% water and extruded through a $\frac{1}{8}$ inch orifice. The extrusions are cut into $\frac{1}{8}$ inch pellets, which are then dried.

EXAMPLE 36.—PELLETS

Pellets with a moderately rapid rate of release are prepared as follows:

	Percent
3-butyl-5-cyanouracil	12
Polyvinyl alcohol (low viscosity)	2
Water	16
Prilled sodium nitrate (2-4 mesh)	70

The active ingredient is first ball milled with the polyvinyl alcohol and water to form a thin paste, which is then added slowly to a ribbon blender agitating the prilled sodium nitrate. Steam heat can be applied to a jacket on the ribbon blender to hasten the drying. Blending and drying are continued until the coating adheres firmly. 3-isopropyl-5-bromouracil can be similarly formulated.

EXAMPLE 37.—PELLETS

	Percent
3-norbornyl-5-methoxymethyluracil	25.0
Anhydrous sodium sulfate	10.0
Alkyl naphthalene sulfonic acid, Na salt	1.0
Non-swelling Ca, Mg bentonite	64.0

These components are prepared as pellets by first blending and grinding them in a micropulverizer, moistening them with 18-22% water and then extruding them through a die having $\frac{1}{8}$ -inch holes. The extrusions are cut at the die face into $\frac{1}{8}$ -inch lengths and dried.

Other compounds suitable for formulation in a similar manner are

3-(1,4,5,6-tetrachloro-7,7-dimethoxybicyclo[2,2,1]hept-5-en-2-ylmethyl)-5-chlorouracil	
3-cyclohexyl-5-fluorouracil	
3-(2-indanyl)-5-hydroxymethyluracil	
3-(m-chlorophenyl)-5-bromouracil	
3-cyclobutyl-5-nitouracil	
3-(2,3-dichloro-3a,4,5,6,7,7a-hexahydro-1,4-methano-5-indanyl)-5-methoxymethyluracil	
3-phenyl-5-bromo-2-thiouracil	
3-chloronorbornyl-5-bromouracil	
3-butyl-5-methyluracil	
3-(decahydro-1,4-5,8-dimethanonaph-2-ylmethyl)-5-methyluracil	
3-(5,6,7,8-tetrahydronaphthyl)-5-methoxymethyluracil	

Any of the pellet compositions of Examples 33-37 can be applied by hand at a level of 25 pounds of active ingredient per acre for control of annual and perennial weeds along guard rails, safety fences, and highway markers and dividers.

The same compositions, when applied by airplane at concentrations of 12-18 pounds of active material per acre, give effective control of willow and oak.

EXAMPLE 38.—PELLETS

	Percent
3-(4-methoxycyclohexyl)-5-methoxymethyluracil	25
Methyl cellulose, low viscosity	3
Kaolin clay	72

These components are blended and micropulverized, then pug-milled with 15% to 20% water, and extruded through $\frac{1}{8}$ -inch die holes. The extrusions are cut into $\frac{1}{8}$ -inch segments, then dried.

The following uracils can also be formulated in this way.

3-(4-isopropylcyclohexyl)-5-hydroxymethyluracil	
3-(4-methoxycyclohexyl)-5-methyluracil	
3-(5,6,7,8,9,9-hexachloro-1,2,3,4,4a,5,6,7,8,8a-decahydro-5,8-methanonaphth-2-ylmethyl)-5-hydroxymethyluracil	

3-(4-methoxycyclohexylmethyl)-5-methoxyuracil	
3-[2-(4-bromocyclohexyl)ethyl]-5-nitouracil	
3-(1,2,3,4-tetrahydronaphthyl)-5-methyluracil	

These formulations, applied in 60 gallons of water at the rate of 25 pounds (active) per acre, control crab grass, barnyard grass, foxtail, pigweed, and lamb's quarters growing along boardwalks.

EXAMPLE 39.—GRANULES

	Percent
10 3-allyl-5-chlorouracil	20
Attapulgite clay	78
Alkyl naphthalene sulfonic acid, Na salt	1
Lignin sulfonic acid, Na salt	1

15 The ingredients are mixed in a ribbon blender until they are homogeneous and are then charged to a pug mill, where sufficient water is blended in to form a thick paste. The paste is discharged from the pug mill in the form of extrusions which are dried and broken by means of a rotary crusher into irregular granules roughly $\frac{1}{4}$ inch to $\frac{1}{8}$ inch in diameter.

3-isopropyl-5-nitouracil is also formulated into herbicidal granules by this method.

EXAMPLE 40.—GRANULES

25 The procedure of Example 41 is used with the following ingredients to give herbicidal granules of high density:

	Percent
30 3-butyl-5-chlorouracil	12
Sand (20-30 mesh)	81
Sodium silicate (28% SiO ₂ ; ratio SiO ₂ /Na ₂ O=3.25)	7

EXAMPLE 41.—GRANULES (FAST RELEASE)

	Percent
35 3-(sec.-amyl)-5-methyluracil, sodium salt	20
10-20 mesh granular, expanded vermiculite	80

The active ingredient is dissolved in water and the solution is then sprayed on the vermiculite while it is tumbled in a blender. The product is then dried.

EXAMPLE 42.—GRANULES

40 This product is prepared in the same manner as in Example 43, using the following ingredients:

	Percent
45 3-(sec.-butyl)-5-chlorouracil, Na salt	2
Granular 15-30 mesh Attaclay	98

EXAMPLE 43.—GRANULES

	Percent
50 3-phenyl-5-chlorouracil, sodium salt	25
8-20 mesh expanded vermiculite	75

55 This composition is prepared by dissolving the active ingredient in water and spraying it on tumbling vermiculite and then drying the product.

Other compounds suitable for the preparation of this type of granule are

3-(p-methoxybenzyl)-5-methyl-2-thiouracil, sodium salt	
3-benzyl-5-nitouracil, potassium salt	
3-cyclooctyl-5-thiocyanouracil, sodium salt	
60 3-propynyl-5-cyano-2-thiouracil, sodium salt	
3-(3-methoxypropyl)-5-bromouracil, lithium salt	
3-(γ -decahydronaphthyl)-5-chlorouracil, sodium salt	
3-(bornyl)-5-fluorouracil, sodium salt	
3-(5,6,7,8,10,10-hexachlorodecahydro-1,4-5,8-dimethano-2-naphthyl)uracil, sodium salt	
3-(3,4-xylyl)-5-methyluracil, potassium salt	
3-(p-butylbenzyl)-5-methoxymethyluracil, sodium salt	

70 Any of the granular compositions of Examples 39-43 can be applied by hand or by specially built spreaders at concentrations of 25 to 30 pounds of active ingredient per acre, for the control of broadleaf and grass weeds in lumber yards, along railroad rights-of-way, fire lanes and around billboards, and in parking areas and roadsides. 75 They can also be applied as soil treatments, at 20-30

pounds of active material per acre, for control of young woody plants such as oak, maple, and willow.

EXAMPLE 44.—GRANULES

	Percent
3-norbornyl-5-(methylthiomethyl)uracil	25
Lignin sulfonic acid, sodium salt	1
Alkyl naphthalene sulfonic acid, sodium salt	1
Attapulgite clay	73

After blending, these ingredients are charged to a pug mill and sufficient water is added to form a thick paste. The paste is extruded through a suitable orifice, broken, and dried.

The following uracils can be similarly formulated:

3-(3,4,5-trichlorophenyl)-5-methyluracil	15
3-(p-fluorophenyl)-5-ethylthiouracil	3
3-(5-nitrofurfuryl)-5-butylthiouracil	1
3-(p-chlorobenzyl)-5-iodouracil	1
3-(3,4-dichlorobenzyl)-5-bromomethyluracil	1
3-[p-(sec.-butoxy)benzyl]-5-bromouracil	1
3-(3-methyl-4-chlorophenyl)-5-methyluracil	1
3-(p-nitrobenzyl)-5-methoxymethyluracil	1
3-isopropyl-5-allyluracil	1
3-isopropyl-5-thiomethyluracil	1
3-cyclopentyl-5-chloromethyluracil	1
3-isopropyl-5-phenylthiomethyluracil	1
3-cyclohexyl-5-carboxymethylthiomethyluracil	1
3-(5-nitro-2-furfuryl)-5-butylthiouracil	1

Twenty pounds (active) of these formulations, applied as the weeds emerge, give excellent control of crab grass, foxtail, barnyard grass, lamb's quarters, flower-of-the-hour and chickweed growing around guard rails and highway signs.

EXAMPLE 45.—GRANULES

	Percent
3-cyclohexyl-5-bromouracil	2.00
Alkyl naphthalene sulfonic acid, Na salt	0.02
Sodium chlorate, 40%-sodium metaborate 60%	97.98

The mixture of sodium chlorate and sodium metaborate is charged to a drum blender. The uracil and surfactant are blended, micropulverized, slurried in water, and then sprayed on the granular mass in the blender.

This formulation controls weeds around sign posts, bridges abutments, trestle supports, signal lights, and hand switches along a railroad. The granules are distributed by hand at about 2 pounds per 100 square feet and give outstanding control of broomsedge, foxtail, ragweed, pigweed, knotweed, morning glory, brambles, and seedling Johnson grass.

EXAMPLE 46.—PELLETS

	Percent
3-(tert.-butyl)-5-bromouracil	10.0
Phenylidimethylurea	10.0
Kaolin clay	77.0
Low viscosity methyl cellulose	3.0

The ingredients are blended, micropulverized, pug-milled with 15 to 20% water, and extruded through $\frac{1}{8}$ -inch holes. The extrusions are then cut to $\frac{1}{8}$ -inch lengths and dried.

These pellets are scattered along a powerline right-of-way at 200 pounds per acre. Excellent control of small oaks, elms, maples, and poplar encroaching on the right-of-way is obtained.

EXAMPLE 47.—TANK MIX

A wettable powder is prepared by blending and micropulverizing the following ingredients:

	Percent
3-cyclohexyl-5-bromouracil	80.00
Diocetyl sodium sulfosuccinate, 85-15 condensate with sodium benzoate	1.00
Low viscosity methyl cellulose	0.25
Attapulgite clay	18.75

Twenty-five pounds of this wettable powder and 23.5 pounds of an 85% formulation of 2,2-dichloropropionic acid, sodium salt, are mixed thoroughly in 150 gallons of water. This spray mixture, applied at 150 gallons per acre along a highway shoulder, gives good control of a heavy population of Johnson grass, lamb's quarters, ragweed, barnyard grass, smartweed, pigweed, and goatweed. The shoulder remains free of these troublesome weed species for an extended period.

EXAMPLE 48.—TANK MIX

Wettable powders are prepared by separately blending and micropulverizing the following groups of ingredients:

	(1)	Percent
3-cyclohexyl-5-bromouracil	60.00	
Alkyl naphthalene sulfonic acid, Na salt	1.50	
Partially desulfonated sodium lignin sulfonate	1.00	
Kaolin clay	37.50	
	(2)	Percent
3-(sec.-butyl)-5-bromo-6-methyluracil	80.00	
Sodium dodecylbenzene sulfonic acid	1.50	
Low viscosity methyl cellulose	0.25	
Attapulgite clay	18.25	

These two wettable powders are mixed in 100 gallons of water. Both powders are added to the water in the amount of 10 pounds of active ingredient.

This spray mixture is applied to a railroad right-of-way at 100 gallons per acre. It gives exceptional control of Johnson grass, Bermuda grass, goldenrod, spotted spurge, smartweed, and ragweed. The area remains free of weeds for an extended time.

	EXAMPLE 49.—WETTABLE POWDER	Percent
3-phenyl-5-bromouracil	80.0	
Calcium lignin sulfonate	0.5	
Sodium arylalkyl sulfonates	2.0	
CaSO ₄ ·2H ₂ O	2.0	
3:1 weight ratio of attapulgite clay to tricalcium phosphate	15.5	

Applied as a pre-emergence treatment, 3 pounds (active) of this formulation per acre in 60 gallons of water gives excellent control of crab grass, foxtail, carpet weed and pigweed in a newly planted field of peanuts.

EXAMPLE 50.—WETTABLE POWDER

A wettable powder is prepared by blending the following components in a ribbon blender, micropulverizing in a hammer mill until the particles are below 50 microns in size, and then reblending until homogeneous.

	Percent
3-cyclohexyl-5-methyluracil	80.00
Attapulgite clay	17.25
Alkyl naphthalene sulfonic acid, Na salt	2.00
Low viscosity methylcellulose	0.25
Diocetyl sodium sulfosuccinate	0.50

Two pounds of this wettable powder composition in 30 gallons of water are applied as directed spray to grasses and broadleaf weeds growing in safflower. Wild mustard, millet, barnyard, and crab grass are killed. Four to eight pounds of active ingredient per acre give excellent control of quack grass growing along fence rows.

At concentrations of 15 to 20 pounds of active ingredient per acre, this composition also gives excellent control of annual and perennial weeds growing on railroad rights-of-way and industrial sites.

3-isopropyl-5-bromouracil and 3-butyl-5-bromouracil are also formulated as wettable powders and used in this manner, with equivalent results.

29

EXAMPLE 51.—WETTABLE POWDER

	Percent
3-butyl-5-chlorouracil, Ca salt	80
Dodecylbenzene sulfonic acid, Na salt	2
Sodium lignin sulfonate	1
Attapulgite clay	17

These ingredients are prepared as a wettable powder in the same manner as shown in Example 50.

Other insoluble or sparingly soluble uracil salts suitable for such formulation are:

3-cyclohexyl-5-chloro-2-thiouracil, Ca salt
3-butyl-5-bromo-2-thiouracil, Mg salt
3-phenyl-5-ethyluracil, Ca salt
3-fenethyl-5-hydroxymethyluracil, sodium salt
3-(3-chloro-4-nitrophenyl)-5-methyluracil manganese salt
3-(3-chloro-4-methoxyphenyl)-5-bromo-2-thiouracil, iron salt

EXAMPLE 52.—WETTABLE POWDER

	Percent
3-cyclohexyl-5-thiocyanouracil	80.0
Diocetyl sodium sulfosuccinate concreted with sodium benzoate	0.4
Terinary acetylenic glycol	0.5
Oleylester of sodium isethionate	1.0
Attapulgite clay	18.1

This wettable powder is also prepared in the manner described in Example 50.

EXAMPLE 53.—WETTABLE POWDER

A wettable powder is prepared by blending the following components in a ribbon blender, followed by micropulverizing in a hammer mill. The ground product is air-reduced until the particles are below 10 microns in size and is then reblended until homogeneous:

	Percent
3-phenyl-5-chlorouracil	50.00
Synthetic precipitated hydrated silicon dioxide	45.75
Low viscosity methylcellulose	0.25
Alkyl naphthalene sulfonic acid, Na salt	2.00
Polyoxyethylene esters of mixed fatty and rosin acids	2.00

EXAMPLE 54.—WETTABLE POWDER

	Percent
3-norbornenylmethyl-5-hydroxymethyluracil	50.0
Alkyl naphthalene sulfonic acid, sodium salt	1.0
Sodium salt of polymerized alkyl naphthalene sulfonic acid	0.5
Calcined, non-swelling Montmorillonoid type clay (Pikes Peak clay)	48.5

This wettable powder is prepared in the same manner as described in Example 53.

Other active materials which make satisfactory wettable powders according to this procedure are

3-naphthylmethyl-5-methoxymethyluracil
3-(m-chlorophenyl)-5-bromouracil
3-allyl-5-thiocyanouracil
3-benzyl-5-methyl-2-thiouracil
3-(2-cyanoethyl)-5-methoxymethyluracil
3-(3a,4,5,6,7,7a-hexahydro-1,4-methano-5-indenyl)-5-chlorouracil
3-(3a,4,5,6,7,7a-hexahydro-1,4-methano-5-indanyl)-5-hydroxymethyluracil
3-(p-anisyl)-5-chlorouracil
3-butyl-5-methyluracil
3-phenyl-5-bromouracil
3-(p-methylbenzyl)-5-methyluracil

EXAMPLE 55.—WETTABLE POWDER

A wettable powder is prepared by blending the following components in a ribbon blender, micropulverizing them in a hammer mill until the particles are all

30

below 50 microns in size, and then reblending until the powder is homogeneous:

	Percent
3-(β -phenethyl)-5-chlorouracil	25
Kaolin clay	70
Diocetyl ester of sodium sulfosuccinic acid	1
Sodium lignin sulfonate	4

EXAMPLE 56.—WETTABLE POWDER

A wettable powder is made by blending the following ingredients in a ribbon blender:

	Percent
3-butyl-5-chloro-2-thiouracil	50
Diatomite	46
Polymerized sodium salts of alkyl naphthalene sulfonic acid	2
Glyceryl monostearate	2

After blending, the composition is micropulverized in a hammer mill until the particles are all less than 50 microns in size. The product is finally reblended in a ribbon blender until homogeneous.

EXAMPLE 57.—WETTABLE POWDER

	Percent
3-isopropyl-5-fluoro-2-thiouracil	60
Synthetic calcium silicate	38
Polyvinyl alcohol (low viscosity)	1
Alkyl naphthalene sulfonic acid, Na salt	1

The components are blended in a ribbon blender, micropulverized in a hammer mill until the particles are below 50 microns in diameter, and then reblended in a ribbon blender until homogeneous.

EXAMPLE 58.—WETTABLE POWDER

A wettable powder is prepared by blending the following ingredients in a ribbon blender:

	Percent
3-cyclooctyl-5-nitouracil	60.00
Attapulgite clay	38.90
Diocetyl ester of sodium sulfosuccinic acid	0.40
Low viscosity methylcellulose	0.30
Aliphatic substituted butylenediols and octyediols	0.40

The blended mixture is ground in a hammer mill until the particles have a diameter of less than 50 microns. The ground product is then reblended until homogeneous.

EXAMPLE 59.—WETTABLE POWDER

A wettable powder formulation is prepared by blending the following components in a ribbon blender:

	Percent
3-cycloheptyl-5-propyluracil	50
Kaolin clay	46
Diocetyl ester of sodium sulfosuccinic acid	1
Sodium lignin sulfonate	3

The blended mixture is ground in a hammer mill until the particles are less than 50 microns in size. The mixture is then reblended until homogeneous.

Any of the wettable powder compositions of Examples 49 and 51-59 can be dispersed in 150 gallons of water and sprayed from a pressure sprayer. When applied as a foliar spray at a level of 20-25 pounds of active ingredient per acre, such a composition gives excellent control of seedling stands, quack grass, Bermuda grass, Johnson grass, water grass, foxtail, and crab grass.

EXAMPLE 60.—WETTABLE POWDER

	Percent
3-isopropyl-5-methyluracil, 1-1 addition compound with octyl amine	40.0
Alkyl naphthalene sulfonic acid, sodium salt	1.0
Low viscosity methyl cellulose	0.3
Attapulgite clay	58.7

These components are blended, micropulverized, and reblended to give a homogeneous powder.

This wettable powder is applied as a pre-emergence treatment, at a rate of 5 pounds of active herbicide per acre in 40 gallons of water, to the area surrounding an outdoor electrical transformer and switching station. When so applied, it gives excellent control of seedling Bermuda grass, seedling bindweed, wild mustard, giant foxtail, crab grass, barnyard grass, and chickweed.

EXAMPLE 61.—WETTABLE POWDER

A wettable powder is prepared by blending the following ingredients in a ribbon blender:

	Percent
3-decy1-5-chlorourasil	70.00
Attapulgite clay	28.25
Alkyl naphthalene sulfonic acid, Na salt	1.50
Low viscosity methylcellulose	0.25

The blended mixture is micropulverized in a hammer mill until the particles are all less than 50 microns in size, and is then remixed in a ribbon blender until homogeneous.

EXAMPLE 62.—WETTABLE POWDER

	Percent
3-(3,4-dichlorophenyl)-5-chlorouracil	50
Kaolin clay	48
Diethyl ester of sodium sulfosuccinic acid	1
Sodium lignin sulfonate	1

The ingredients are mixed together in a ribbon blender and micropulverized in a hammer mill until the particles are below 50 microns in size.

The ground product is then remixed in a ribbon blender until homogeneous.

EXAMPLE 63.—WETTABLE POWDER

	Percent
3-(sec.-butyl)-5-bromouracil	40.00
2-methylmercapto-4-ethylamino-6-isopropylamino-s-triazine	40.00
Alkyl naphthalene sulfonic acid, Na salt	1.75
Low viscosity methyl cellulose	0.25
Attapulgite clay	18.00

These ingredients are formulated into a wettable powder by blending and micropulverizing them until the particles are under 50 microns in size.

This formulation controls pernicious weed populations in oil refineries around oil storage tanks, pipelines, vents, and valves. Thirty pounds of the 80% powder in 100 gallons of water per acre gives rapid kill of fingergrass, foxtail, lovegrass, crab grass, broomsedge, sand spur, marestail, ragweed, beggarticks, and spurge.

EXAMPLE 64.—WETTABLE POWDER

	Percent
3-norbornyl-5-bromouracil	16.0
Disodium monomethylarsonate	64.0
Alkyl naphthalene sulfonic acid, Na salt	0.5
Sodium lignin sulfonate	1.0
Kaolin clay	16.0
Synthetic fine silica	2.5

These components are blended and micropulverized until the particles are under 50 microns in size.

This composition controls crab grass in arbor vitae when dispersed in 100 gallons of water and sprayed pre-emergence at 5 pounds per acre when the crab grass starts to emerge. The composition also controls chickweed.

EXAMPLE 65.—WETTABLE POWDER

	Percent
3-cyclohexyl-5-chlorouracil	25.0
3-(3,4-dichlorophenyl)-1-methoxy-1-methylurea	25.0
Kaolin clay	40.0
Synthetic fine silica	3.0
Alkyl naphthalene sulfonic acid, Na salt	2.0
Partially desulfonated sodium lignin sulfonate	5.0

These ingredients are blended, micropulverized, and then passed through an air attrition mill to reduce the particle size to approximately 5 microns or less.

This formulation is sprayed on a sugar cane crop at 1.5 pounds of active ingredients in 60 gallons of water per acre when the cane is about 12 inches tall and the weeds are less than 4 inches tall. Excellent control of foxtail, water grass, annual morning glory, butter print, pigweed, ragweed, crab grass, and spotted spurge is obtained without perceptible injury to the cane.

EXAMPLE 66.—WETTABLE POWDER

	Percent
3-cyclohexyl-5-bromouracil, 1:1 complex with pentachlorophenol	80
Alkyl naphthalene sulfonic acid, sodium salt	2
Partially desulfonated sodium lignin sulfonate	2
Attapulgite clay	16

These ingredients are blended and micropulverized until the particles wet screen through 325 mesh.

The formulation is applied at the rate of 30 pounds of the active compound (1:1 complex) per acre in 60 gallons of water, to annual and perennial weeds growing around electric towers and highway sign posts. Excellent initial kill of the weeds is obtained. Weed species which are controlled are cheat crab grass, seedling Johnson grass, brome grass, foxtail, ryegrass, quack grass, bluegrass, purslane, Spanish needle, mustard and velvet-leaf.

This same spray mixture is also applied to a railroad right-of-way at 100 gallons per acre. It gives exceptional control of seedling Johnson grass, seedling Bermuda grass, goldenrod, spotted spurge, smartweed, and ragweed. The area remains free of weeds for an extended time.

EXAMPLE 67.—WETTABLE POWDER

	Percent
3-sec.-butyl-5-iodouracil	40.00
Diethyl ester of sodium sulfosuccinic acid	0.40
Low viscosity methyl cellulose	0.30
Aliphatic substituted butyndiols and octyndiols	0.40
Kaolin clay	58.90

These ingredients are blended, ground in a hammer mill until the particle diameters are 50 microns or less, and then reblended.

The following uracils can be similarly formulated:

50	3-(3-chloro-1-methylpropyl)-5-ethyluracil
	3-(4-bromobutyl)-5-methyluracil
	3-hydroxyethyl-5-methylthiouracil
	3-ethoxycarbonylmethyl-5-bromouracil
55	3-dimethylaminoethyl-5-methoxymethyluracil
	3-methoxyethyl-5-hydroxymethyluracil
	3-(p-bromophenyl)-5-hydroxymethyluracil
	3-(3,4-dibromophenyl)-5-hydroxymethyluracil
	3-(p-nitrophenyl)-5-methyluracil
	3-(3,4-dimethylbenzyl)5-(2-hydroxypropyl)uracil
60	3-propynl-5-methyluracil
	3-cyano-5-bromouracil

3-(4-isopropyl-2-methylbenzyl)-5-bromouracil

These formulations, applied as foliar sprays at 25 pounds (active) per acre in 60 gallons of water to emerging weeds, give excellent control of crab grass, foxtail, chickweed and volunteer small grains growing around loading platforms.

The embodiments of the invention in which an exclusive property or privilege is claimed are:

1. A method for the control of undesirable vegetation, said method comprising applying to a locus to be protected from such vegetation, a herbicidally effective amount of a compound selected from the group consisting of

(a) compounds of the formula

where

R is selected from the group consisting of alkyl of 1 through 10 carbon atoms, substituted of alkyl of 1 through 10 carbon atoms, wherein said substituent is selected from the group consisting of bromine, chlorine, hydroxy, alkoxy, alkoxy carbonyl, di-alkylamino, and cyano, aryl of 5 through 14 carbon atoms, substituted aryl of 5 through 14 carbon atoms, wherein said substituent is selected from the group consisting of chlorine, bromine, fluorine, phenyl, alkoxy, alkyl, nitro, trifluoromethyl, 1,2-tetramethylene, and 1,2-trimethylene, arylalkyl of 5 through 15 carbon atoms, substituted arylalkyl of 5 through 15 carbon atoms, wherein said substituent is selected from the group consisting of chlorine, alkyl, nitro, and alkoxy, tetrahydronaphthylalkyl, alkenyl of 3 through 10 carbon atoms, alkynyl of 3 through 10 carbon atoms, cycloalkyl of 3 through 12 carbon atoms, substituted cycloalkyl of 3 through 12 carbon atoms, wherein substituent selected from the group consisting of bromine, chloride, methoxy, and alkyl, cycloalkenyl of 4 through 12 carbon atoms, substituted cycloalkenyl of 4 through 12 carbon atoms, wherein said substituent is selected from the group consisting of bromine, chlorine, methoxy, and alkyl, cycloalkyl alkyl of 4 through 13 carbon atoms, cycloalkenyl alkyl of 5 through 13 carbon atoms, (substituted cycloalkyl)alkyl of 5 through 14 carbon atoms, wherein said substituent is selected from the group consisting of bromine, chlorine, methoxy, and alkyl, (substituted cycloalkenyl)alkyl of 5 through 14 carbon atoms, wherein said substituent is selected from the group consisting of bromine, chlorine, methoxy, and alkyl, and cyano;

R₁ is selected from the group consisting of chlorine, fluorine, bromine, iodine, methyl, ethyl, propyl, butyl, methoxy, ethoxy, propoxy, butoxy, nitro, alkoxy methyl of 2 through 6 carbon atoms, hydroxy alkyl of 1 through 6 carbon atoms, alkenyl of 3 through 6 carbon atoms, thiocyanato, cyano, methylthiol, alkylthio of 1 through 4 carbon atoms, methylthiomethyl, chloromethyl, bromomethyl, fluoromethyl, phenylthiomethyl, and carbomethyl, phenylthiomethyl, and carboxymethylthiomethyl,

with the proviso that R₁ can be hydrogen when R is selected from the group consisting of cycloalkyl, cycloalkenyl, cycloalkyl alkyl, and cycloalkenyl alkyl;

and

X is selected from the group consisting of oxygen and sulfur;

and

(b) the sodium, potassium, lithium, calcium, magnesi-

um, barium, strontium, iron, manganese, and quaternary ammonium salts of the compounds in (a).

2. The method of claim 1 wherein the herbicidal active compound is 5-bromo-3-phenyluracil.

3. The method of claim 1 wherein the herbicidal active compound is 3-butyl-5-methyluracil.

4. The method of claim 1 wherein the herbicidal active compound is 3-cyclohexyl-5-bromouracil.

5. The method of claim 1 wherein the herbicidal active compound is 3-cyclohexyl-5-methyluracil.

6. The method of claim 1 wherein the herbicidal active compound is 3-norbornyl-5-methyluracil.

7. The method of claim 1 wherein the herbicidal active compound is 3-sec.-butyl-5-methyluracil.

8. The method of claim 1 wherein the herbicidal active compound is 3-sec.-butyl-5-chlorouracil, sodium salt.

9. The method of claim 1 wherein the herbicidal active compound is 3-tert-butyl-5-bromouracil.

10. The method of claim 1 wherein the herbicidal active compound is 3-tert-butyl-5-chlorouracil, sodium salt.

3-cyclopropylmethyl-5-methyluracil

11. A method for the control of undesirable vegetation, said method comprising applying to a locus to be protected from such vegetation, a herbicidally effective amount of a compound selected from the group consisting of:

(a) compounds of the formula

where

R is selected from the group consisting of alkyl of 1 through 10 carbon atoms, substituted alkyl of 1 through 10 carbon atoms, wherein said substituent is selected from the group consisting of bromine, chlorine, hydroxy, alkoxy, alkoxy carbonyl, di-alkylamino, and cyano,

aryl of 5 through 14 carbon atoms, substituted aryl of 5 through 14 carbon atoms, wherein said substituent is selected from the group consisting of chlorine, bromine, fluorine, phenyl, alkoxy, alkyl, nitro, trifluoromethyl, 1,2-tetramethylene, and 1,2-trimethylene,

arylalkyl of 5 through 15 carbon atoms, substituted arylalkyl of 5 through 15 carbon atoms, wherein said substituent is selected from the group consisting of chlorine, alkyl, nitro, and alkoxy,

tetrahydronaphthylalkyl, alkenyl of 3 through 10 carbon atoms, alkynyl of 3 through 10 carbon atoms, cycloalkyl of 3 through 12 carbon atoms, substituted cycloalkyl of 3 through 12 carbon atoms, wherein said substituent is selected from the group consisting of bromine, chloride, methoxy, and alkyl,

1,2-tetramethylene, and 1,2-trimethylene, arylalkyl of 5 through 15 carbon atoms, substituted arylalkyl of 5 through 15 carbon atoms, wherein said substituent is selected from the group consisting of chlorine, alkyl, nitro, and alkoxy,

tetrahydronaphthylalkyl, alkenyl of 3 through 10 carbon atoms, alkynyl of 3 through 10 carbon atoms, cycloalkyl of 3 through 12 carbon atoms, substituted cycloalkyl of 3 through 12 carbon atoms, wherein said substituent is selected from the group consisting of bromine, chlorine, methoxy, and alkyl,

1,2-tetramethylene, and 1,2-trimethylene, cycloalkenyl of 4 through 12 carbon atoms, substituted cycloalkenyl of 4 through 12 carbon atoms, wherein said substituent is selected from the group consisting of bromine, chlorine, methoxy, and alkyl,

cycloalkyl alkyl of 4 through 13 carbon atoms, cycloalkenyl alkyl of 5 through 13 carbon atoms, and

(substituted cycloalkyl)alkyl of 5 through 14 carbon atoms, wherein said substituent is selected from the group consisting of bromine, chlorine, methoxy, and alkyl,

35

(substituted cycloalkenyl)alkyl of 5 through 14 carbon atoms, wherein said substituent is selected from the group consisting of bromine, chlorine, methoxy, and alkyl, and cyano;

5

R_1 is selected from the group consisting of chlorine, fluorine, bromine, iodine, methyl, ethyl, propyl, butyl, methoxy, ethoxy, propoxy, butoxy, nitro, alkoxyethyl of 2 through 6 carbon atoms, 10 hydroxy alkyl of 1 through 6 carbon atoms, alkenyl of 3 through 6 carbon atoms, thiocyanato, cyano, methylthiol, alkylthio of 1 through 4 carbon atoms, methylthiomethyl, chloromethyl, bromomethyl, 15 fluoromethyl, phenylthiomethyl, and carboxymethylthiomethyl, with the proviso that R_1 can be hydrogen when R is selected from the group consisting of cycloalkyl, cycloalkenyl, cycloalkyl alkyl, and 20 cycloalkenyl alkyl;

and

X is selected from the group consisting of oxygen and sulfur;

(b) the sodium, potassium, lithium, calcium, magnesium, barium, strontium, iron, manganese, and quaternary ammonium salts of the compounds in (a);

(c) compounds of the formula

30

where

R and R_1 are as defined above, and

NB is a nitrogenous base having an ionization constant $K_b \geq 10^{-9}$ in water; and

40

36

(d) compounds of the formula

where

R and R_1 are as defined above,
 X is selected from the group consisting of hydrogen, chlorine, nitro, alkyl of 1 through 3 carbon atoms, bromine and OR_2 ; where R_2 is alkyl of 1 through 3 carbon atoms;

Y is selected from the group consisting of chlorine and alkyl of 1 through 3 carbon atoms;
 m is a whole number 1 through 5, and
 n is selected from the group consisting of 1 and 2.
